CENTRALIZED TRAFFIC CONTROLLING
SYSTEM FOR RAILROADS

William D. Hailes, Brighton, and Frederick W. Brixner, Gates, N. Y., assignors to General Railway Signal Company, Rochester, N. Y.

Application March 22, 1938, Serial No. 197,404

26 Claims. (Cl. 177—353)

This invention relates to centralized traffic controlling systems for railroads, and it more particularly pertains to such systems of the coded two-wire simplex communication type.

In a coded centralized traffic controlling system for railroads, track switches and signals distributed throughout the territory included in the system are controlled from a control office over a code type communication system. Those track switches and signals relatively close to each other, together with the apparatus for governing their operation, constitute a field station of such system. The manual control of the track switches and signals for the several stations is accomplished by the transmission of electrical impulses, forming codes, from the control office to each of those stations, one at a time, over a line circuit which extends from the control office through the several stations to the most distant field station. Such manual control of the system is supplemented by the usual automatic block signal system and other local means ordinarily provided to guard against unsafe train movements and improper operation of track switches and signals.

This invention provides a coded centralized traffic controlling system by which controls and indications are transmitted over a two-wire main line circuit extending between the control office and the field stations in such a manner as to include in series a line relay at each main line field station and at the control office. A two-wire repeater line circuit is also provided, together with apparatus which constitutes a repeater station for tying it into the main line circuit. Such a repeater line circuit includes in series a line relay at each repeater line field station and at the repeater station. The repeater line circuit provides that the system can include a greater territory than would be practical to include in one single line circuit.

For the transmission of controls from the control office to any one of the field stations, a predetermined number of impulses of selected polarity are applied to the line circuit, each impulse operating step-by-step mechanisms at the control office and at the field stations in synchronism through a cycle of operation. The first part of such a series of impulses constituting a station selecting code, and the second part of such a series of impulses constitutes a control code for the particular station selected to receive the controls.

For the transmission of indications from any one of the field stations to the control office, a

control office battery supplies energy to the main line circuit, and a repeater station battery supplies energy to the repeater line circuit. The line circuit is opened and closed at that field station to effect its energization with a predetermined number of impulses separated by time spaces, both of a selected length. Each impulse operates step-by-step mechanisms at the control office and at the transmitting field station in synchronism through a cycle of operation, irrespective of the length of the impulses and time spaces. The first part of such a series of impulses constitutes a station registration code, and the second part of such a series of impulses constitutes an indication code to be registered at the control office.

The system is of the simplex type, that is, the transmission of controls and indications is effected only on different cycles of operation. It is to be understood, however, that the scope of various novel features of the present invention is not limited to systems of the simplex type.

The line circuit is normally maintained energized when the transmitting means at the control office and at the field stations is inactive. Such energization is of a negative polarity. The period of time during which both transmitting means are inactive is conveniently called a period of rest.

A field station can be initiated into a cycle of operation for the transmission of indications only if the line circuit is first energized with negative polarity during a period of rest. Thus the negative energization of the line circuit during a period of rest provides a permission for a start from the field stations. As a means for registering a field start at the control office, the field station having indications to transmit, momentarily opens the line circuit.

The control of the polarity of energization of the line circuit is maintained at all times at the control office. Thus, the control office determines whether or not a permission polarity is to be applied to the line circuit at the end of each cycle of operation. If there are controls to be transmitted at the end of a cycle of operation, positive polarity is applied to the line circuit. If there are no controls to be transmitted at the end of a cycle of operation, the permission negative polarity is applied to the line circuit.

There is a conditioning period at the beginning of each cycle of operation for so conditioning the system that the transmitter can maintain control of the line circuit throughout the cycle. Such conditioning takes place during a period of

energization of the line circuit. If the line circuit is energized with positive polarity during such a period, the entire system is conditioned for a control cycle. If the line circuit is energized with negative polarity during such a period, the entire system is conditioned for an indication cycle.

Thus, if a positive polarity is applied to the line circuit at the end of any cycle of operation, the system immediately enters a conditioning period for a control cycle, and transmission from all field stations is suppressed because of lack of permission polarity. If the control office and a field station start a cycle of operation simultaneously, the control office gains control of the system for the transmission of controls by applying positive energization to the line circuit to rule out the field station start and condition the system for the transmission of controls.

After the conditioning has been completed, the line circuit is impulsed by the transmitter. The periods of deenergization during such impulsing are conveniently called "off" periods, and the periods of energization are conveniently called "on" periods.

During the transmission of indications, the length of the long "on" and "off" periods is determined by the time required for the dropping away of slow release timing relays which are selectively controlled in accordance with indications to be transmitted. At the control office, long "on" and "off" periods are detected by detector relays which are maintained energized so long as the periods for which they are provided are short, but which are dropped away whenever the periods for which they are provided are long.

In accordance with this invention, means is provided whereby the transmission of indications is so distributed between stations that each of a group of stations having indications to transmit at the beginning of a series of cycles can transmit only one cycle of operation until the system has passed through a prolonged period of rest. Changes occurring at field stations during a series of cycles are effective for starting the transmission of indication cycles only after the system has passed through a prolonged period of rest. If there are a group of stations at a particular field location, each of those stations has an opportunity to transmit one and only one indication cycle during a series, whenever that particular field location gains control of the line circuit.

An object of this invention is to provide an efficient two-wire simplex communication system, using a control office battery as a source of energization for the line circuit for the transmission of both controls and indications, whereby the control office transmitter gains and maintains control of the line circuit by the selection of the polarity of its energization, even in case of a simultaneous start between the control office transmitter and a field station transmitter.

Another object of this invention is to provide a means dependent upon the operation of comparatively quick acting relays having comparatively constant characteristics for detecting the difference between long and short, "off" and "on" periods.

A further object is to so distribute the facilities of the system for the transmission of indications among the field stations, that each station transmits its indications with a minimum delay after a change has occurred in the position of any of the devices at that station.

A still further object of this invention is to extend the territory that can be efficiently included in such a system by the use of repeater stations.

Other objects, purposes, and characteristic features of the present invention will be in part obvious from the accompanying drawings and in part pointed out as the description of the invention progresses.

In describing the invention in detail, reference will be made to the accompanying drawings, in which those parts having similar features and functions are designated throughout the several figures by like letter reference characters which are generally made distinctive either by reason of preceding numerals representative of their location or by reason of succeeding numerals representative of the order of their operation, and in which:

Figs. 1A and 1B, when placed end to end, illustrate in a simplified manner certain of the features provided by this invention relative to the line circuit extending between the control office and the field stations;

Figs. 2, 3 and 4 illustrate the apparatus and circuit arrangement employed at the control office, Fig. 2 being relative to the selection of the polarity to be applied to the line circuit, Fig. 3 being relative to the stepping and to the reception of indications from the field stations, and Fig. 4 being relative to the registration of indications received from the field stations;

Figs. 5A and 5B, when placed side by side, illustrate the apparatus employed at a typical field station arranged and controlled in accordance with the present invention;

Fig. 6 illustrates a means provided by this invention, also shown in Figs. 5A and 5B, for distributing indication cycles among all stations having indications to transmit at the beginning of a series of successive cycles;

Fig. 7 illustrates a means provided by this invention for distributing indication cycles among all stations having indications to transmit during a series of successive cycles.

Fig. 8 illustrates how the distribution of indication cycles is accomplished where a plurality of stations are provided at a particular field location;

Fig. 9 illustrates a means provided by this invention for repeating control and indication impulses into a branch line circuit. For convenience in considering the application of the repeater station the drawings have been provided in such a manner that Fig. 9, when placed between Figs. 3 and 5A illustrates how the repeater station may be placed between the control office and the field station illustrated in detail, and Fig. 9, when placed at the side of Fig. 5B, illustrates how the repeater station can be connected between any particular field stations.

Figs. 10A and 10B, when placed one above the other, constitute a chart illustrating the sequence of operation of the relays during a specific control cycle.

Figs 11A and 11B, when placed one above the other, constitute a chart illustrating the sequence of operation of the relays during a specific indication cycle.

In order to simplify this disclosure, reference is made from time to time to functions common to all parts of a similar character by use of the letter reference characters without preceding or succeeding numerals. It is to be understood that such a reference applies to any parts designated

in the drawings by reference characters which are similar except for numerals associated therewith.

For the purpose of simplifying the illustration and facilitating in the explanation, the various parts and circuits constituting the embodiment of the invention have been shown diagrammatically and certain conventional illustrations have been employed, the drawings having been made more with the purpose of facilitating the disclosure as to the principles and mode of operation, than with the idea of illustrating the specific construction and arrangement of parts that would be employed in practice. Thus the various relays and their contacts are illustrated in a conventional manner, and symbols are used to indicate connections to the terminals of batteries, or other sources of electric current instead of showing all of the wiring connections to those terminals.

The symbols (+) and (−) are employed to indicate the positive and negative terminals respectively of suitable batteries or other source of direct current; and the circuits with which these symbols are used always have current flowing in the same direction. The symbols (B+) and (B−) indicate connections to the opposite terminals of a suitable battery or other direct current source which has a central or intermediate tap designated (CN); and the circuits with which these symbols are used may have current flowing in one direction or the other depending upon the particular terminal used in combination with the intermediate tap (CN). When alternating current is used in place of direct current, the particular symbols employed represent the relative instantaneous polarities.

Apparatus

Control office equipment.—The control office equipment (see Figs. 2, 3 and 4) includes a control machine having a group of control levels for each field station, a miniature track layout corresponding to the actual track layout in the field, and various indicator lamps or equivalent devices together with apparatus and circuits to accomplish the desired operation of the system.

The part of the control office illustrated shows more particularly that portion of the control machine which is typical of the apparatus associated with a single field station having a track switch, a crossover or the like, together with the general transmitting apparatus employed in common by all of the field station units provided for the system.

In accordance with the present invention various functions can be controlled from the control machine, but for the purpose of simplifying the present disclosure only a switch machine control lever SML together with self-restoring start and cancel buttons B and CNB respectively have been shown, it being understood that the control of the track switch from the control machine by the operation of lever SML is typical of the means which is provided for controlling other devices at the various field stations.

Associated with each group of control levers is a change storing relay CH and a code determining relay CD. The actuation of a start button B causes the energization of its corresponding change relay CH, which in turn energizes its associated code determining relay CD, provided the system is at rest. If the system is in operation the relay CH remains energized to cause the initiation of a control cycle and the picking up

of its associated relay CD when the system reaches a period of rest.

In the event that several starting buttons are actuated simultaneously or in rapid succession, the change relays CH and code determining relays CD together with a code determining stick relay CDS, are so interlocked that only one code determining relay may be picked up for any one particular cycle of operation, and that interlock is so arranged that the relays CD are picked up in a predetermined sequence, depending upon their position in the circuits.

Associated with the contacts of each code determining relay CD (see Figs. 2 and 3) are code jumpers which selectively connect the circuits associated with the contacts on that relay to the relays PC and NC which are provided for applying energy to the line circuit from a line battery CB. The relay PC, when energized, causes the application of positive energy to control line wire 10 of the line circuit, and the relay NC, when energized, causes the application of negative energy to that line wire.

In response to the energization of the line circuit, a quick acting neutral relay F is picked up, and its energization during a cycle of operation causes the energization of the quick acting repeater relay FA.

In order to effect the proper timing of certain of the relays employed at the control office, and in order to provide other features relative to the operation of the system, the relays SA, SB, SC and SD are provided. Relay SA has such slow acting characteristics as to remain in a picked up position between the energized impulses of the line circuit. Should the time between the impulses of the line circuit be of a length of time longer than that required for the transmission of control and indication codes, the relay SA drops away and terminates the cycle of operation.

The slow acting relay OC serves to restore the system to normal in the event that an energized impulse longer than that required for the transmission of control and indication cycles is impressed upon the line circuit during the transmission of a series of impulses.

A bank of stepping relays has been shown as having the relays V1, V2, V3, V4, a last stepping relay LV, and a half-step relay VP. The number of steps being determined by the number of stations to be connected to the line circuit and the number of different devices to be controlled and indicated.

An impulsive relay E is jointly controlled by the stepping relays and the half-step relay VP, and its functions are to apply and remove impulses to and from the line circuit during a control cycle and, together with its associated repeater relay EP, to start the long time intervals that are detected by relays TON and TOF during long "on" and "off" periods of an indicated cycle.

Relay TON remains energized during an indication cycle if the line impulses are of comparatively short length, and drops away during each long impulse.

Relay TOF remains energized during an indication cycle if the time spaces between the line impulses are comparatively short, and drops away during each long time space between impulses.

The relays LON and LOF respond, during an indication cycle, to the dropping away of relays TON and TOF respectively, and the positioning of relays LON and LOF determines the position

for the pilot relays PON and POF (see Fig. 4) respectively.

For the purpose of illustrating the feature of station registration, the relays PON and POF are positioned on the first and second steps of the indication cycle in accordance with the positions of the message receiving relays LON and LOF respectively. If a larger number of field stations is employed than can be registered by this bank of pilot relays, more steps may be employed and additional pilot relays may be provided. Following the positioning of the pilot relays, a registration execution relay RX is picked up to provide energy for a station relay ST which is selected in accordance with the station to be registered. Although a station relay ST is provided for each field station and is selected in accordance with that station registering code, only one ST relay has been shown, thus the operation of that relay is to be considered as typical of the operation provided for the relays ST provided for each of the other field stations which may be included in the system.

Following the registration of a station by the picking up of a station relay, suitable indication storing relays, such as relays RON and ROF, for example, which are of the two-position polarized magnetic stick type, are positioned on the remaining steps of the indication cycle for storing the indications received from the field station which has been registered.

Relay OR (see Fig. 2) is an auxiliary relay which is normally energized and is dropped away at the beginning of each cycle and again picked up in the period of rest. Relay OR provides the line circuit with a low degree of energization during periods of rest and also provides means whereby a series of indication cycles can be interrupted for the transmission of a control cycle.

Relay C (see Fig. 2) is provided for the purpose of starting the system into operation to transmit a control cycle, and relay CF is for the purpose of starting the system into a cycle of operations in response to a start from a field station.

Various resistors R are provided at the control office for providing various features relative to the control of the relays and relative to the drainage of the line circuit.

The control office equipment also includes various sources of current supply, bus wires and circuit connections, indicator lamps, over-load protection and such other devices as may be needed for the proper functioning of such a system.

Field station equipment.—The field station apparatus illustrated in Figs. 5A and 5B of the accompanying drawings is typical of all field stations of the system and may be adapted for use at the first, second, or any other location included in the main line circuit, or may be adapted for use at any stations included in the repeater line circuit beyond the repeater station illustrated in Fig. 9. The only necessary change from the typical field station shown is in the position of the two groups of code jumpers, which are arranged differently at each location in order to provide for the selection of that particular station at times when control codes are transmitted, and for the registration of a station at the control office at the beginning of the transmission of an indication code. For convenience in the description, it has been assumed that the field station illustrated is the first field station along the line circuit extending from the control office, and is so designated by reason of the preceding numeral 1 employed.

With reference to Fig. 5B, a turnout track is illustrated as connected to a main track by a track switch TS which is operated from one extreme locked position to the other by a suitable switch machine SM.

The switch machine SM is governed by a switch machine control relay SMR which is of the two-position polar magnetic stick type and which is governed from the control office by means of the 10 communicating system provided by this invention. The relay SMR controls the operation of the switch machine SM by energizing its normal or reverse operating wires in any suitable well known manner so as to provide proper protection 15 for the safe operation of the track switch TS.

Suitable signals are associated with the track switch TS for governing traffic thereover and are provided with automatic block signalling means with selections made in accordance with the position 20 of the track switch TS and the condition of the detector track section. In addition to the automatic means for governing the signals associated with the track layout, the signals are also controlled from the control office by means of the 25 communicating system provided by this invention in a similar manner to that illustrated for the control of the track switch TS, various modifications being employed to meet the requirements of practice.

30 Associated with the signals governing traffic over the track switch TS is a suitable normally energized indicating relay M which is deenergized whenever a signal is cleared for governing traffic over that track switch.

35 A detector track circuit having a track relay T is provided in the usual manner for the track section including the track switch TS.

The communication part of the system at the field station includes a three-position biased-to-neutral polar line relay 1F together with its quick acting repeating relay 1FA. Slow acting relays 1SA and 1SB correspond to similar relays provided at the control office in that they are picked up in the conditioning period at the start of a 40 cycle of operation, and are held up throughout that cycle.

As a means responsive to the transmission of a station selecting code from the control office during a control cycle, the relays 1SO and 1SOS are provided and are controlled in such a manner that relay 1SO remains energized during a 50 control cycle only so long as the code impressed upon the line circuit corresponds with the code assigned to that field station. The energizing 55 circuit for the relays SO and SOS includes code jumpers which, by their positions, determine the particular code required to select that station.

The field station includes a bank of stepping relays comprising half-step relay 1VP and stepping relays V1, V2, V3, V4 and LV. These relays are operated in synchronism with the similar stepping bank provided for the control office, with the exception that the stepping relay bank at the field station is dependent upon station 60 selection during the transmission of either control or indication cycles.

A change relay 1CH and its repeater relay 1CHP is provided to register a change in the position of certain of the traffic controlling devices at the field station in order to initiate the 65 transmission of an indication cycle.

A lockout relay LO is provided for each field station for the purpose of making effective the transmission of indications from but one of several 70 stations having indications to transmit.

When a station has new indications to transmit, the relay LO for that station is energized momentarily, during a period of rest, and the momentary picking up of that relay opens the line circuit to register, in the control office, the start of an indication cycle. Relay LO picks up again at the end of the conditioning period and it remains picked up during the stepping only at the location that is permitted to transmit indications. When relay LO is in the picked up position it terminates the line thus disconnecting the more distant portion of the line and thereby ruling out all more distant locations.

Auxiliary line lockout means is provided by the combined operation of relays RL and L at the beginning of a cycle of operation for purposes pointed out hereinafter.

Relay S is provided in order to supply an additional circuit to support the SA relay and prevent the SA relay from releasing during long "off" time spaces occurring during an indication cycle. The S relay also provides the means for preventing the release of the indication storing repeater relay CHP during a control cycle.

Relays E at the field stations perform a function similar to relay E in the control office in that they effect the impulsion of the line circuit, such impulsion being rendered effective only for the transmission of indications from the field stations to the control office.

Relays LON and LOF at the field stations govern the length of the impulses and the time spaces between the impulses respectively during the transmission of indications from the field station. The energization of the relays LON and LOF is dependent upon code jumpers for selecting the station registration code for the indication cycle, and on the positions of the relays or devices, of which the positions are to be indicated, such as relays T and M. Relay LON when energized from such means during an "off" period provides that the next impulse should be long, and in a similar manner when relay LOF is energized during an "on" period it provides that the next "off" period shall be long.

A relay OC is provided for each field station and is controlled in a similar manner to the relay OC provided for the control office, with the exception that its control circuits combined with its slow acting characteristics provide that it remains energized throughout a series of cycles and is released at the end of such a series.

With reference to the modification illustrated in Fig. 7, a relay DS is provided which is picked up only at a field station which is transmitting indications, and is maintained in an energized position throughout a series of indication cycles.

With reference to the modification illustrated in Fig. 8, in addition to the change relays CH and CHP, lockout relays CHL, LC and LCS are provided for causing the distribution of indication cycles in a manner to be hereinafter described in detail.

The field station also includes suitable bus wires, circuit connections, over-load devices, and other devices and apparatus necessary for a centralized traffic controlling system as contemplated in accordance with the present invention.

Repeater station equipment.—The repeater station transmits to the repeater line circuit the control code impulses which are applied to the line circuit at the control office, and in doing so employs relays 3PC, 3NC and 3C in a similar manner and for similar purposes as has here-

tofore been described for relays performing similar functions at the control office.

Relays 3F, 3F2 and 3FA are responsive to the energization of the line circuits with which they are associated in a similar manner to the relays of a similar character provided for the field stations, and slow acting relays 3S, 3SA and 3SB are also provided for purposes similar to the purposes for which relays of a similar character are provided for the field station.

Relay 3FB is a repeater of the deenergized position of relay 3FA during the transmission of impulses, and it is provided to insure the maintaining in a picked up position throughout an indication cycle of relay 3OC, which is controlled in a similar manner to relay OC of the field station.

Relay 3CF registers the beginning of an indication cycle as initiated from a station included in the repeater line circuit, and relay 3LO locks out more distant stations in the main line circuit during the transmission of indication cycles from a station included in the repeater line circuit.

25 The auxiliary relay 3OR is provided for maintaining similar characteristics of the repeater line circuit to the characteristics of the main line circuit as provided by relay OR in the control office.

30 Relay 3E is used in impulsion the main line circuit during an indication cycle, and the impulsion of that relay is governed by the relay 3F2 which is included in the repeater line circuit.

35 Various resistors R are provided for purposes which are in part obvious from the accompanying drawings and which will be pointed out more in detail as the description of the invention progresses.

40 The repeater station also includes suitable circuit connections, over-load devices, and other devices and apparatus necessary for a centralized traffic controlling system as contemplated in accordance with the present invention.

45 It is to be understood that the relays illustrated have proper operating characteristics to fulfill the requirements of the system according to the mode of operation herein described and according to the requirements of practice. It is also to be understood that characteristics of certain of the relays can be adjusted according to the requirements of practice by such means, for example, as the application of shunts across the windings of those relays to effect a greater delay in their dropping away.

50 It is believed that the nature of the invention, its advantages and characteristic features can best be understood by considering the mode of operation of the system illustrated.

Operation

The communication system provided by the present invention is normally at rest, from which it can be initiated into a cycle of operation from the control office or from any one of the field stations whenever there are new controls or new indications respectively ready to be transmitted. If new controls for several different field stations are ready for transmission at the same time, they are transmitted on separate cycles, one cycle for each station to be served. If several field stations have indications ready for transmission at the same time they are transmitted from such field stations to the control office, one cycle for each station. The lockout feature is effective to

allow only one field station to obtain access to the line circuit during any one cycle.

Normal at rest conditions.—When the system is at rest, the line circuit is maintained energized in order that any field station can register at the control office the need for an indication cycle by a momentary interruption of the line circuit.

The line circuit is energized with negative polarity when the system is at rest to permit any of the field stations to initiate an indication cycle. Such energization can be conveniently called a permission minus energization, because the line circuit can be opened by a field station only when the line circuit is energized with negative polarity during the rest period, as is hereinafter described in detail. Such energization is maintained by a stick circuit for relay F in the control office which includes a limiting resistance R for the purpose of conserving energy from the battery CB, it being obvious that once the relays F in the line circuit are positioned at the end of a cycle of operation, as will be hereinafter described, less energy is required for maintaining those relays in their last operated position.

In order to simplify the description of the present invention reference is made from time to time to the positive or negative energization of the line circuit, which is to be understood as meaning the application of positive or negative energy respectively to the side of the line circuit which includes the relays F and which leaves the control office as wire 10 (see Fig. 3).

During a period of rest, relay NC (see Fig. 2) is maintained in a picked up position by a stick circuit which, similar to the line circuit, includes a limiting resistance R2 for conserving energy and also for making relay NC quick in dropping away. The stick circuit for maintaining relay NC in a picked up position during a period of rest is closed from (+), through a circuit including back contact 11 of relay SD, back contact 12 of relay C, back contact 13 of relay CF, front contact 14 of relay F, resistance R2, front contact 15 of relay NC, and winding of relay NC, to (—).

The line circuit is normally energized (see Fig. 3), from the negative terminal of battery CB, through a circuit including back contact 16 of relay PC, front contact 17 of relay NC, winding of relay IF (see Fig. 5A), back contact 146 of relay LO, the winding of the relay F and the back contact of the relay LO for each of the other stations, return line wire 18, front contact 19 of relay NC, back contact 20 of relay PC, winding of relay F, front contact 21 of relay F, and resistance R, to the positive terminal of battery CB.

Relay OR (see Fig. 2) is normally energized in order to open the pick up circuits for relays NC and F during a period of rest. A circuit is closed for energizing relay OR during such a period, from (+), through a circuit including back contact 22 of relay C, back contact 23 of relay CF, front contact 24 of relay F, and winding of relay OR, to (—). A stick circuit is also closed for relay OR from (+), through a circuit including back contact 28 of relay SA, front contact 29 of relay OR, and winding of relay OR, to (—). The stick circuit maintains relay OR picked up at the beginning of a cycle for reasons hereinafter pointed out.

At the field station illustrated (see Figs. 5A and 5B), relays T, M, ICH, IF and IRL are nor-

mally energized. Relay T is of course energized from the usual track circuit battery and, although its position has been shown as that assumed when the track circuit is unoccupied, it is to be understood that the system can as well be in a period of rest when the track circuit is occupied so as to cause the deenergization of relay T, such period of rest being reached after the indication has been transmitted of the change in the position of the relay T. A similar mode of operation is effected relative to the position of relay M for repeating the stop position of the signals associated with the track layout, that is, relay M can be in either a picked up or a dropped away position during a period of rest.

Relay ICH is maintained in its energized position during a period of rest by a circuit closed from (+), through a circuit including front contact 25 of relay M, front contact 26 of relay T, front contact 27 of relay ICH, and lower winding of relay ICH, to (—). It is of course obvious that relay ICH is maintained in an energized position during a period of rest when relays T and M are in either an energized or a deenergized position and is dropped away upon a change in the position of either of those relays.

Relay IRL (see Figs. 5A and 5B) is energized, when the line circuit is energized with negative polarity during a period of rest so as to cause the polar contacts of relay IF to be in a left hand position, by a circuit closed from (+), through a circuit including back contact 29 of relay ISB, polar contact 30 of relay IF in a left hand position, wire 147, back contact 429 of relay LV, back contact 31 of relay V4, back contact 32 of relay V3, back contact 33 of relay V2, back contact 34 of relay V1, wire 148, back contact 35 of relay IL, and winding of relay IRL, to (—). A stick circuit is closed for relay IRL from (+), through a circuit including back contact 36 of relay ISB, winding of relay IL, front contact 37 of relay IRL, and winding of relay IRL, to (—), but such stick circuit is ineffective for the picking up of relay IL as long as the pick up circuit for relay IRL remains closed to shunt out that stick circuit. Relay IL becomes energized, however, as soon as the pick up circuit for relay IRL is opened as will be hereinafter pointed out.

Manual start.—The system can be manually initiated into a cycle for the transmission of control impulses by the positioning of the control levers for the particular station with which the operator desires to communicate and by following such operation by the momentary actuation of the start button B associated with those levers.

The arrangement of the circuits for the control of relays CH, CD and CDS is such as to provide that only the manual start for one station is rendered effective at any one time, but it is so arranged that the defining of starts for the communication of controls to various stations is stored until the system is available for the transmission of those controls. The order in which several stored starts are transmitted is herein-after pointed out during the consideration of circuits involved.

After the operator has positioned all of the levers for a particular station, such, for example, as for the station shown nearest the control office, the momentary depression of the start button B1 associated therewith (see Fig. 2) closes a circuit for the energization of relay CH1 from (+), through a circuit including contact 38 of button B1 in a depressed position, winding of relay CH1 and contact 39 of button CNB in a

normal position, to (-). The picking up of relay CH1 closes an obvious stick circuit for that relay through a circuit including back contact 40 of relay CD1.

The picking up of relay CH1 closes a circuit for the energization of the upper winding of relay CD1 from (+), through a circuit including back contact 41 of relay SC, back contact 42 of relay CF, back contact 43 of relay CDS, back contact 44 of relay CH2, front contact 45 of relay CH1, upper winding of relay CD1, and contact 39 of button CNB in a normal position, to (-). Relay CD1, upon picking up, closes a stick circuit from (+), through a circuit including back contact 46 of relay LV, winding of relay CDS, front contact 47 of relay CD1, lower winding of relay CD1, and contact 39 of button CNB in a normal position, to (-). Back contacts 48 and 49 of relays C and SC respectively also apply energy to the stick circuit for the relays CD in order to cause only a brief interruption in that circuit during the clearing out period.

Relay CDS picks up when the stick circuit for any of the relays CD is closed, because its winding is included in those circuits, and the picking up of relay CDS opens the pick up circuit for all relays CD at back contact 43 to insure that only one CD relay can be operated at any one time.

If the operator desires to initiate the transmission of controls to any other stations, he can do so by positioning the levers for those stations and depressing the associated buttons such as button B2, but the picking up of the relay CH, such as relay CH2, cannot effect the energization of the relay CD associated therewith, such as relay CD2, until the pick up circuit is closed for those relays by the dropping away of the code determining stick relay CDS.

If two or more control office starts are effected simultaneously or are effected prior to the dropping away of relay CDS, the front contact of the relay CH which is included in the pick up circuit of the relay CD associated therewith, and which is nearest the source of energy for that circuit, locks out all other relays CD for which starts have been initiated. To consider an example of such a mode of operation assume relays CH1 and CH2 to become energized simultaneously or to become energized while relay CDS is picked up. The picking up of relay CH2 opens the circuit for relay CD1 at front contact 44 and closes the circuit for relay CD2 at that same front contact to cause the energization of relay CD2 as soon as other contacts in that circuit are closed. The operating characteristics of relays CH, CD and CDS are such that the above mode of operation is provided. Relays CH are slow in dropping away after their stick circuits are opened by the picking up of their associated relays CD in order to allow sufficient time for the stick circuits for relays CD to be closed.

The picking up of relay CDS closes a circuit for the energization of relay C, which initiates a control cycle, from (+), through a circuit including back contact 50 of relay SC, front contact 51 of relay CDS, back contact 52 of relay CF, and winding of relay C, to (-). A stick circuit is closed for relay C from (+), through a circuit including back contact 53 of relay SB, front contact 54 of relay C, and winding of relay C, to (-). The stick circuit for relay C also is energized from (+), through a circuit including front contact 55 of relay SA, in order to maintain that relay energized throughout a control cycle.

In describing the circuits for the relays CH, CD and CDS, it was noted that the circuits for each of those relays included a contact on cancel button CNB which is normally closed. It is therefore obvious that the depression of that button causes the restoration of all control starts which have been initiated. If the operator depresses the cancel button during a control cycle, the dropping of the relay CD prevents the completion of the cycle and causes the clearing out of the system.

Polarity selection of stepping impulses.—It has been predetermined by the arrangement of circuits provided by this invention that certain polarities are always applied to the line circuit under certain conditions throughout the cycle of operation; for example, positive polarity is always applied to the line circuit during the conditioning period at the start of a control cycle, negative polarity is always applied to the line circuit throughout an indication cycle, and the polarity of the impulses applied during the "on" periods in a control cycle is dependent upon the predetermined selection of those polarities by code jumpers and lever contacts associated with the code determining relay CD for each station.

The polarity of the line circuit is dependent upon the position of relays PC and NC, and, more specifically, the line circuit is energized positive when relay PC is picked up and it is energized negative when relay NC is picked up.

Relay PC is energized, after relays C, E and OC have picked up at the start of a conditioning period for a control cycle, by a circuit closed from (+), through a circuit including front contact 56 of relay OC, back contact 57 of relay SD, front contact 58 of relay C, front contact 60 of relay E, back contacts 427, 61, 62, 63 and 64 of relays LV, V4, V3, V2 and V1 respectively, and winding of relay PC, to (-). The closing of front contact 66 of relay SC prior to the picking up of relay SD during the conditioning period provides that relay PC remains energized until relay E is dropped away.

Relay NC is energized, after relay CF is picked up at the start of the conditioning period for an indication cycle, by a circuit closed from (+), through a circuit including front contact 56 of relay OC, back contact 57 of relay SD, back contact 58 of relay C, front contact 65 of relay CF, and winding of relay NC, to (-). Relay NC is maintained energized throughout an indication cycle through the same circuit heretofore described and including front contact 66 of relay SC which maintains the circuit closed during the stepping.

The polarity of the first group of impulses for the "on" periods during a control cycle is dependent upon the position of jumpers associated with the relay CD picked up for that cycle; for example, the jumper 67, when in the position shown by solid lines, selects the energization of relay PC, and when in the position shown by dotted lines selects the energization of relay NC.

In a similar manner, the polarity of a second group of impulses during a control cycle is dependent upon the position of levers or equivalent devices on the control panel, for example, the lever SML, when in the position shown by solid lines selects the energization of relay PC, and when in the position shown by the dotted line selects the energization of relay NC.

The above mentioned first group of impulses are provided for the purpose of selecting the field station with which communication is desired, and they form a station selecting code. A different

code is provided for each station in accordance with different positions of the jumpers for the various relays CD. The number of impulses to be included in that code is dependent upon the number of stations to be selected, that is, the number of stations that can be selected by a particular code is equal to two raised to the power equal to the number of impulses used for the station selecting codes.

The above mentioned second group of impulses is provided for the transmission of controls to the particular station selected by the station selecting code, and the number of impulses required for the control code is dependent upon the number of functions at each field station to be controlled from the control office.

As an example of how the relays PC and NC are energized during a control cycle, assume the relay CD1 to be picked up for a control cycle and lever SML to be in the normal position shown. On the first step, after relays V1 and E have picked up in a manner hereinafter described, a circuit is closed for energizing relay PC from (+), through a circuit including front contact 56 of relay OC, front contact 66 of relay SC, front contact 58 of relay C, front contact 60 of relay E, back contacts 427, 61, 62 and 63 of relays LV, V4, V3 and V2 respectively, front contact 64 of relay V1, front contact 68 of relay CD1, jumper 67, and winding of relay PC, to (-).

On the second step, after relays V2 and E have picked up in a manner hereinafter described, a circuit is closed for energizing relay PC from (+), through a circuit including front contact 56 of relay OC, front contact 66 of relay SC, front contact 58 of relay C, front contact 60 of relay E, back contacts 427, 61 and 62 of relays LV, V4 and V3, respectively, front contact 63 of relay V2, front contact 69 of relay CD1, jumper 70 and winding of relay PC, to (-).

On the third step, after relays V3 and E have picked up in a manner hereinafter described, a circuit is closed for energizing relay NC from (+), through a circuit including front contact 56 of relay OC, front contact 66 of relay SC, front contact 58 of relay C, front contact 60 of relay E, back contacts 427 and 61 of relays LV and V4 respectively, front contact 62 of relay V3, front contact 71 of relay CD1, jumper 72, and winding of relay NC, to (-).

On the fourth step, after relays V4 and E have picked up in a manner hereinafter described, a circuit is closed for energizing relay PC from (+), through a circuit including front contact 56 of relay OC, front contact 66 of relay SC, front contact 58 of relay C, front contact 60 of relay E, back contact 427 of relay LV, front contact 61 of relay V4, front contact 73 of relay CD1, contact 74 of lever SML in a left hand position, and winding of relay PC, to (-).

It is obvious that the circuit for the energization of relay PC or NC for each "on" period is opened by the picking up of the stepping relay during the following "off" period. For example, the picking up of relay IV opens the circuit closed during the preceding "on" period for relay PC at back contact 64. The dropping away of the relays PC and NC, however, is always effected by the dropping away of relay E to open front contact 60.

Having considered how the polarities are determined for each of the steps, consideration will now be given to the mode of operation of the stepping relay bank in response to the energization of the line circuit.

Operation of stepping relay bank.—The line circuit is energized at the beginning of a cycle of operation with polarities determined by the position of the contacts 16, 20, 19 and 17 of relays 5 PC and NC. The energization of the line circuit during a control cycle is dependent upon the closing of front contact 60 of impulsing relay E, and the means heretofore described for determining the polarity of the impulses is effective 10 for determining the polarity of the next impulse during the time when front contact 60 of relay E is open. The periodic opening and closing of contact 60 of relay E causes the time spaced impulses to be impressed upon the line circuit. Such impulsing, which is dependent upon the 15 operation of the stepping relay bank, is herein-after considered in detail. The stepping relay bank is responsive to such impulsing of the line circuit during a control cycle in such a manner that one stepping relay is picked up during each "off" period.

In a similar manner the stepping relay bank is operated in response to the impulsing of the line circuit by an impulsing relay at a field station during an indication cycle. Under such 20 conditions, relay NC remains picked up throughout the cycle and the time spaced impulses are effected by an impulsing relay, such, for example, as the relay 1E (see Figs. 5A and 5B).

For the purpose of considering the operation of the stepping relay bank, it is sufficient to assume time spaced impulses impressed upon the line circuit, irrespective of the source of the impulsing.

Assume relay C to pick up to initiate a control cycle. The picking up of that relay opens the normally energized stick circuit for relay NC at back contact 12 (see Fig. 2), and closes a circuit for the energization of relay OC from (+), 30 through a circuit including back contact 11 of relay SD, front contact 12 of relay C, and winding of relay OC, to (-). After the picking up of relay SD, relay OC becomes energized only during the time between impulses, when relay 35 F is dropped away, through a circuit closed from (+), through a circuit including front contact 56 of relay OC, front contact 57 of relay SD, back contact 75 of relay F, and winding of relay OC, to (-). The slow dropping away characteristics 40 of relay OC allows that relay to drop away during a cycle, only if an abnormally long energized period occurs during the impulsing. The dropping away of relay SD at the end of a cycle causes relay OC to drop away, provided there is a 45 period of rest between cycles.

Relay E picks up, in response to the picking up of relay C at the beginning of a control cycle, in a manner hereinafter described in detail when considering the impulsing of the line circuit. In response 50 to the picking up of relays OC and E at the beginning of a control cycle, relay PC is energized through a circuit heretofore described.

Relay F, in the line circuit, is dropped away 55 momentarily upon the reversal of polarity, and the line circuit becomes energized with full voltage, upon the picking up of relay PC, by a circuit closed from the positive terminal of battery CB (see Fig. 3), through a circuit including front contact 76 of relay C, winding of relay F, front contact 20 of relay PC, back contact 17 of relay NC, line wire 10, winding of each of the relays F, a back contact of relay LO at each of the field stations connected in series, line wire 18, back contact 19 of relay NC and front contact 16 of 60 relay PC, to the negative terminal of battery CB.

When relay PC picks up, circuits are closed successively for the energization of relays FA, SA, SB, SC and SD. The pick up circuit for relay FA is closed from (+), through a circuit including front contact 77 of relay PC, front contact 78 of relay F and winding of relay FA, to (-). Relays SA, SB, SC and SD are successively energized through obvious circuits including front contacts 79, 80, 81 and 82 of relays FA, SA, SB and SC respectively.

The quick action of relay FA causes that relay to pick up and drop away in accordance with the opening and closing of front contact 78 of relay F. Relays SA, SB, SC and SD, however, are so slow in dropping away that they remain picked up between the impulses of either a control or an indication cycle, but drop away between cycles or upon an abnormally long period of deenergization during the impulsing of the line circuit.

The picking up of relay SB closes another energizing circuit for relay FA, from (+), through a circuit including front contact 83 of relay SB, front contact 78 of relay F, and winding of relay FA, to (-). This circuit provides that relay FA is energized on each impulse of a cycle, irrespective of the polarity of that impulse.

The picking up of relay SA opens the stick circuit for relay OR at back contact 28 (see Fig. 2), and relay OR remains deenergized throughout the cycle.

The picking up of relay SD during the conditioning period closes a pick up circuit for relay VP (see Fig. 3), from (+), through a circuit including front contact 84 of relay SD, front contact 85 of relay SC, front contact 86 of relay FA, back contact 87 of relay V1, and winding of relay VP, to (-). The picking up of relay VP closes a stick circuit for that relay from (+), through a circuit including front contact 84 of relay SD, front contact 85 of relay SC, front contact 88 of relay VP, back contact 87 of relay V1, and winding of relay VP, to (-).

After the line circuit is deenergized at the end of the conditioning period (first "off" period), the dropping of relay FA closes another stick circuit for relay VP from (+), through a circuit including front contact 84 of relay SD, front contact 85 of relay SC, back contact 86 of relay FA, front contact 89 of relay VP, and winding of relay VP, to (-). A purpose of the first described stick circuit for relay VP is to maintain that relay energized during the dropping away of relay FA, and a purpose of the second stick circuit is to maintain that relay picked up after the picking up of a stepping relay which opens the stick circuit which includes front contact 88.

The dropping away of relay FA during the first "off" period closes a circuit for energizing relay V1 from (+), through a circuit including front contact 90 of relay SC, back contact 91 of relay FA, front contact 92 of relay VP, back contact 93 of relay V4, back contact 94 of relay V2, and winding of relay V1, to (-). The picking up of relay V1 closes a stick circuit for that relay from (+), through a circuit including front contact 75 of relay SC, front contact 96 of relay V1, and winding of relay V1, to (-).

The time required for the relay FA to release is determined by the shunt circuit closed, during a control cycle, from (-), through a circuit including resistor R3, front contact 97 of relay C, and winding of relay FA, to (-), in order to allow sufficient time for the stepping to become effective at the field stations under adverse battery voltage conditions or when the characteristics of

the line circuit are such as to cause the dropping of the relays F at the field stations to lag the dropping of the relay F at the control office.

During the next period of energization of the line circuit (first "on" period), the picking up of relay FA causes the dropping away of relay VP by opening its stick circuit at back contact 86. The stick circuit including front contact 88 of relay VP had been opened at back contact 87 of relay V1 by the picking up of that relay.

During the next period of deenergization of the line circuit (second "off" period), the dropping away of relay FA closes a circuit for energizing relay V2 from (+), through a circuit including front contact 90 of relay SC, back contact 91 of relay FA, back contact 92 of relay VP, back contact 98 of relay LV, back contact 99 of relay V3, front contact 100 of relay V1, and winding of relay V2, to (-). The picking up of relay V2 closes a stick circuit for that relay from (+), through a circuit including front contact 101 of relay V1, front contact 102 of relay V2, and winding of relay V2, to (-).

During the next period of energization of the line circuit (second "on" period), the picking up of relay FA causes the energization of relay VP by a circuit closed from (+), through a circuit including front contact 84 of relay SD, front contact 85 of relay SC, front contact 86 of relay FA, back contact 103 of relay V3, front contact 104 of relay V2, and winding of relay VP, to (-). The picking up of relay VP closes a stick circuit for that relay from (+), through a circuit including front contact 84 of relay SD, front contact 85 of relay SC, front contact 88 of relay VP, back contact 103 of relay V3, front contact 104 of relay V2, and winding of relay VP, to (-).

During the next period of deenergization of the line circuit (third "off" period), the dropping away of relay FA closes the same stick circuit as heretofore described for relay VP which maintains that relay energized after relay V3 is picked up. The dropping away of relay FA closes a circuit for energizing relay V3 from (+), through a circuit including front contact 90 of relay SC, back contact 91 of relay FA, front contact 92 of relay VP, back contact 93 of relay V4, front contact 94 of relay V2, and winding of relay V3, to (-). The picking up of relay V3 closes a stick circuit for that relay from (+), through a circuit including front contact 105 of relay V2, front contact 106 of relay V3, and winding of relay V3, to (-).

During the next period of energization of the line circuit (third "on" period), the picking up of relay FA causes the dropping away of relay VP by opening its stick circuit at back contact 86. The other stick circuit for relay VP was opened by the picking up of relay V3 at back contact 103.

During the next period of deenergization of the line circuit (fourth "off" period), the dropping away of relay FA closes the same stick circuit as was heretofore described for maintaining relay VP energized after relay V4 is picked up. A circuit is closed for energizing relay V4 from (+), through a circuit including front contact 90 of relay SC, back contact 91 of relay FA, back contact 92 of relay VP, back contact 98 of relay LV, front contact 99 of relay V3, and winding of relay V4, to (-). The picking up of relay V4 closes a stick circuit for that relay from (+), through a circuit including front contact 105 of relay V3, front contact 107 of relay V4, and winding of relay V4, to (-).

During the next period of energization of the

line circuit (fourth "on" period) the dropping away of relay FA closes a circuit for energizing relay VP from (+), through a circuit including front contact 84 of relay SD, front contact 85 of relay SC, front contact 86 of relay FA, front contact 108 of relay V4, and winding of relay VP, to (-). The picking up of relay VP closes a stick circuit for that relay from (+), through a circuit including front contact 84 of relay SD, front contact 85 of relay SC, front contact 86 of relay VP, front contact 108 of relay V4, and winding of relay VP, to (-).

It is obvious from the above description that each step is taken in a manner similar to that of the preceding step, thus it is apparent that other steps can be added, as required in practice, and that the additional steps will operate in a manner described for those steps that are shown.

During the last period of deenergization of a control cycle (clearing out period), the dropping of relay FA closes a circuit for energizing relay LV from (+), through a circuit including front contact 90 of relay SC, back contact 91 of relay FA, front contact 92 of relay VP, front contact 93 of relay V4, and winding of relay LV, to (-). The picking up of relay LV closes a stick circuit for that relay from (+), through a circuit including front contact 109 of relay V4, front contact 110 of relay LV, and winding of relay LV, to (-).

The dropping away of relay FA during the clearing out period causes the dropping away of relays SA, SB, SC and SD successively.

The picking up of relay LV at the end of a control cycle, causes the restoration of relays CD1 and CDS by opening their circuit at back contact 46 (see Fig. 2). Back contacts 48 and 49 of relays C and SC are open at the time because those relays have not yet been dropped away.

The dropping away of relay SA opens the stick circuit for relay C and that relay drops away because its pick up circuit was opened by the picking up of relay SC during the conditioning period.

The dropping of relay SC causes the dropping away of relay VP by opening its circuit at front contact 85.

The dropping of relay SC also opens the stick circuit for relay V1 at front contact 75, which causes the successive dropping away of relays V2, V3, V4 and LV, due to their circuits having been opened, in turn, at front contacts 101, 105, 145 and 109 of relays V1, V2, V3 and V4 respectively.

The dropping of relay SD at the end of the clearing out period, with relay OR in a deenergized position, closes a circuit for the energization of relay NC (see Fig. 2) with full voltage from (+), through a circuit including back contact 11 of relay SD, back contact 12 of relay C, back contact 13 of relay CF, back contact 111 of relay OR, and winding of relay NC, to (-). The dropping of relay SD also causes the dropping away of relay OC due to the opening of front contact 57.

The picking up of relay NC closes the line circuit for energization with full voltage from the negative terminal of battery CB through a circuit including back contact 16 of relay PC, front contact 17 of relay NC, line wire 18, winding of relay 1F, back contact 146 of relay 1LO, winding of relay F and back contact of relay LO for each of the other field stations included in the line circuit, return line wire 18, front contact 19 of relay NC, back contact 20 of relay PC, winding of relay F and back contact 112 of relay OR, to the positive terminal of battery CB.

The picking up of relay F, under such conditions, causes the picking up of relay OR by the energization of its pick up circuit closed at front contact 24, and the picking up of relay OR opens the above described pick up circuit for relay NC, and the line relays F at back contacts 111 and 112 respectively, thus the system is again restored to normal conditions maintained during a period of rest in which the stick circuit for relays NC and F are maintained energized at a low value of current, as has been heretofore described when considering the normal conditions of the system.

Having thus described the mode of operation of a stepping relay bank for the control office, it is to be understood that a similar mode of operation is employed for the stepping relay bank for each of the field stations, although the stepping at the field stations is made dependent upon station selection, as is hereinafter pointed out.

Impulsing of the line circuit at the control office.—In considering the means for energizing the line circuit with positive or negative polarity, it has been pointed out that the energization of either relays PC or NC is effective only when front contact 60 of relay E is closed (see Fig. 2). Thus the length of each energized impulse of the line circuit throughout a control cycle is dependent upon the length of time that front contact to 60 of relay E remains closed. The line circuit is energized, during a control cycle, each time that relay E is picked up, and it is deenergized each time that relay E is dropped away through the medium of the PC and NC relays.

Relay E is first picked up, during a control cycle, after relay C has picked up to render the start of that cycle effective. The picking up of relay C closes a circuit for energizing relay E (see Fig. 3) from (+), through a circuit including front contact 113 of relay C, back contacts 114, 115, 116, 117 and 118 of relays LV, V4, V3, V2 and V1 respectively, back contact 119 of relay VP, and winding of relay E, to (-). The picking up of relay E closes a circuit hereinafter described for the energization of relay PC, and the picking up of relay PC causes the energization of the line relays F.

The picking up of relay F at the control office (see Fig. 3) causes the successive energization of relays FA, SA, SB, SC and SD in a manner heretofore described, and the picking up of relay SD completes a circuit for relay VP. The mode of operation of relay VP has been pointed out when considering the operation of the stepping relay bank, thus in considering the means for governing the impulsing it is sufficient to assume that relay VP picks up at the end of the conditioning period during either a control or an indication cycle, and that it shifts its position during each "on" period.

The picking up of relay VP at the end of the conditioning period causes the dropping away of relay E by opening the circuit for that relay at back contact 119. Relay E remains dropped away until relay V1 is picked up, after which it is picked up by the energization of a circuit closed from (+), through a circuit including front contact 113 of relay C, back contacts 114, 115, 116 and 117 of relays LV, V4, V3 and V2 respectively, front contact 119 of relay V1, front contact 119 of relay VP, and winding of relay E, to (-).

Relay E remains picked up during the first "on" period until relay VP drops away and causes the dropping away of that relay by opening its control circuit at front contact 119. Relay E re-

mains dropped away until relay V2 is picked up, after which it is picked up by the energization of a circuit closed from (+), through a circuit including front contact 113 of relay C, back contacts 114, 115 and 116 of relays LV, V4, and V3 respectively, front contact 117 of relay V2, back contact 119 of relay VP, and winding of relay E, to (-).

Relay E remains picked up during the second "on" period until relay VP picks up, and causes the dropping away of that relay by opening its control circuit at back contact 119. Relay E remains dropped away until relay V3 is picked up, after which it is picked up by the energization of a circuit closed from (+), through a circuit including front contact 113 of relay C, back contacts 114 and 115 of relays LV and V4 respectively, front contact 116 of relay V3, front contact 119 of relay VP, and winding of relay E, to (-).

Relay E remains picked up during the third "on" period until relay VP drops away and causes the dropping away of that relay by opening its control circuit at front contact 119. Relay E remains dropped away until relay V4 is picked up, after which it is picked up by the energization of a circuit closed from (+), through a circuit including front contact 113 of relay C, back contact 114 of relay LV, front contact 115 of relay V4, back contact 119 of relay VP, and winding of relay E, to (-).

After relay E is dropped away, during the last "on" period, due to the shifting of relay VP, it remains in a deenergized position until the next cycle is initiated, because its control circuit is held open at back contact 114 of relay LV until relay C (during a control cycle) or relay CF (during an indication cycle) have dropped away to open front contact 113 or front contact 120 respectively.

Station selection for controls.—It is obvious that the impulses are received at all of the field stations during a control cycle, because the field station line relays are all included in the line circuit. For convenience in describing the mode of operation of the station selecting means provided by this invention, reference will be made to Figs. 5A and 5B which illustrate a typical field station assumed to be the first in a series from the control office. The station illustrated in those figures is selected for the reception of controls by the station selecting code (+)(+)(-), which is made up at the control office when relay CD1 picks up and establishes connections to the code jumpers (see Fig. 2) associated with that relay.

When the line circuit is energized positive at the start of the conditioning period, as has been heretofore described, the contacts of the polar relay F at each of the field stations shift from a normal left hand position to a right hand position. Such operation causes the immediate picking up of relay L at each location because the shunt circuit for the L relay is opened when the contacts of the F relay at each station shift from a left hand position.

The closing of the polar contact for relay F in a right hand position at each field station closes a circuit for energizing the station selecting relay SO, and its associate relay SOS. Thus relays SO and SOS are picked up at each station during the conditioning period of a control cycle.

During the first "on" period the relays SO for half of the total number of stations are dropped away, due to the selection of the circuits by the code jumpers. During the second "on" period

the relays SO for half of the remaining stations are dropped away. Thus, on each impulse, half of the relays SO remaining picked up at the beginning of that impulse are dropped away, until, by such process of elimination, after the station selecting code has been completely transmitted, only the stepping for the one station for which the controls are intended remains responsive to the impulsion of the line circuit from the control office.

Having thus considered in a general manner the means provided for selecting a station for the reception of control codes, consideration is now given to the detail of the operation at one particular station as a specific example of how each station is selected.

After the shunt is removed from relay 1L (see Figs. 5A and 5B) by the opening of polar contact 30 in a left hand position, that relay picks up immediately.

When the polar contacts of relay 1F are operated to a right hand position in response to the positive energization of the line circuit at the start of the conditioning period, a circuit is closed for energizing relays 1SO and 1SOS from (+), through a circuit including back contact 29 of relay 1SB, polar contact 30 of relay 1F in a right hand position, wire 149, back contacts 428, 121, 122, 123 and 124 of relays LV, V4, V3, V2 and V1 respectively, wire 150, upper winding of relay 1SO and upper winding of relay 1SOS, to (-).

As soon as relay 1SO is picked up, a stick circuit is closed for that relay through its upper winding and the same circuit as above described for picking up that relay, except that the energization of the circuit is provided by front contact 125 of relay 1SO to maintain that circuit energized after relay SB is picked up.

The picking up of relay 1L closes a circuit for the energization of relay 1OC from (+), through a circuit including back contact 126 of relay 1SB, front contact 127 of relay 1L, front contact 128 of relay 1RL, and winding of relay 1OC, to (-). Once relay 1OC is picked up at the beginning of a cycle it remains up throughout the cycle until a period of rest is reached in a similar manner to relay OC, at the control office.

Relay 1FA is energized by an obvious circuit when polar contact 129 of relay 1F is operated to a right hand position. The picking up of relay 1FA closes a circuit for relay 1SA from (+), through a circuit including front contact 130 of relay 1FA, front contact 131 of relay 1SO and winding of relay 1SA, to (-). At the same time relay 1FA closes a circuit for energizing relay 1SB from (+), through a circuit including front contact 132 of relay 1FA, front contact 133 of relay 1SO, and winding of relay 1SB, to (-).

The picking up of relay 1SA closes an obvious circuit including front contact 154 for maintaining relay SB picked up throughout the control cycle. The picking up of relay 1SB causes the dropping away of relays 1L and 1RL by opening their circuit at back contact 36. Relays 1SA and 1SB are slow acting to cause them to remain picked up throughout a cycle in the same manner as relays of a similar character provided for the control office.

The dropping away of relay 1RL closes a circuit for maintaining relay 1OC in a picked up position, due to the energization of that circuit which is closed during each "off" period, from (+), through a circuit including back contact 134 of relay 1FA, front contact 135 of relay 1OC,

back contact 128 of relay 1RL, and winding of relay 1OC, to (-).

The deenergization of the line circuit at the end of the conditioning period causes the dropping away of relays 1F and 1FA successively. The dropping away of relay 1F opens the above described stick circuit for relay 1SO, which includes front contact 125, but relay 1SO is maintained energized through a stick circuit including its lower winding which is closed from (+), through a circuit including front contact 29 of relay 1SB, front contact 136 of relay 1SOS, front contact 137 of relay 1SO, and lower winding of relay 1SO, to (-). Relay 1SOS is also maintained energized immediately after the dropping away of relay 1F by a stick circuit closed from (+), through a circuit including front contact 29 of relay 1SB, front contact 138 of relay 1FA, front contact 139 of relay 1SOS, and lower winding of relay 1SOS, to (-).

The dropping away of relay 1FA closes a stick circuit for relay 1SO from (+), through a circuit including front contact 29 of relay 1SB, back contact 138 of relay 1FA, front contact 137 of relay 1SO, and lower winding of relay 1SO, to (-). The dropping away of relay 1FA also opens the stick circuit for relay 1SOS at front contact 138, which causes that relay to drop away because its pick up circuit is also open. Thus it is obvious that a purpose for relay 1SOS is to maintain relay 1SO energized for the time intervening between the dropping away of relay 1F and the closing of back contact 138 of relay 1FA.

For the purpose of considering the station selecting means provided, it is to be assumed that the stepping relays at the field station pick up successively during the "off" periods, one for each period, beginning with the period following the conditioning impulse. It is also to be assumed, as will be pointed out hereinafter, that the energization of the stepping relays is effective only so long as relay SO at that location remains picked up.

Thus, the picking up of relay V1 during the first "off" period selects a stick circuit for relay 1SO which is closed, immediately upon the operation of polar contact 30 of relay 1F to a right hand position in response to the positive energization of the line circuit, from (+), through a circuit including front contact 125 of relay 1SO, polar contact 30 of relay 1F in a right hand position, wire 149, back contacts 428, 121, 122 and 123 of relays LV, V4, V3 and V2 respectively, front contact 124 of relay V1, jumper 140, wire 150, upper winding of relay 1SO, and upper winding of relay 1SOS, to (-).

Relay 1SO is maintained picked up by the energization of its lower winding during the second "off" period in the same manner as was described in detail for the first "off" period.

The picking up of relay V2 during the second "off" period selects a stick circuit for relay 1SO which is closed, upon the operation of polar contact 30 of relay 1F to a right hand position in response to the positive energization of the line circuit, from (+), through a circuit including front contact 125 of relay 1SO, polar contact 30 of relay 1F in a right hand position, wire 149, back contacts 428, 121 and 122 of relays LV, V4 and V3 respectively, front contact 123 of relay V2, jumper 141, wire 150, upper winding of relay 1SO, and upper winding of relay 1SOS, to (-).

Relay 1SO is maintained picked up by the energization of its lower winding during the third

"off" period in the same manner as was described in detail for the first "off" period.

The picking up of relay V3 during the third "off" period selects a stick circuit for relay 1SO which is closed, upon the operation of polar contact 30 of relay 1F to a left hand position in response to the negative energization of the line circuit, from (+), through a circuit including front contact 125 of relay 1SO, polar contact 30 of relay 1F in a left hand position, wire 147, back contacts 429 and 31 of relays LV and V4 respectively, front contact 32 of relay V3, jumper 142, wire 150, upper winding of relay 1SO and upper winding of relay 1SOS, to (-).

Relay 1SO is maintained picked up by the energization of its lower winding during the third "off" period in the same manner as was described in detail for the first "off" period.

It is therefore obvious that the maintaining of relay SO picked up during the reception of a station selecting code of impulses is entirely dependent upon the correspondence of the polarity of each impulse received with the position of the code jumper at that station for that step. Once the stick circuit for relay SO is opened by the out of correspondence position of one of the code jumpers at that station, that relay drops away and remains dropped away until its pick up circuit is closed at the beginning of the next control cycle.

The relay SO, which remains picked up throughout the reception of each of the station selecting code impulses, is maintained picked up throughout the remainder of the cycle to render the stepping effective at that station during the reception of the elements of the control code. Relay 1SO, for example, is maintained energized throughout the cycle by the stick circuit closed, upon the picking up of relay V4 from (+), through a circuit including front contact 29 of relay 1SB, wire 151, front contact 152 of relay V4, jumper 143, back contact 144 of relay LV, wire 153, front contact 137 of relay 1SO, and lower winding of relay 1SO, to (-). The picking up of relay V4 opens the pick up circuits for relay 1SOS at back contacts 31 and 121 to cause that relay to remain deenergized throughout the remainder of the cycle.

Having thus shown how the continued energization of the relay SO for only a particular one of the several stations is effected for a control cycle in response to the code applied to the line circuit, consideration is now given to the stepping at the field station, and the means provided whereby the stepping is effective during a control cycle only so long as the relay SO at that field station remains picked up.

Stepping at the field stations.—Having described in detail the mode of operation of the stepping relay bank at the control office, such description is to be considered as typical of the mode of operation at the field stations, with the exception of variations herein described.

Assume, for example, the operator at the control office to initiate the transmission of controls to the first of the field stations included in the line circuit, by the depression of button B1 (see Fig. 2) after having positioned the switch and signal control levers for that station.

A quick reversal of the polarity of energization of the line circuit is effected which causes the picking up of relay 1L (see Figs. 5A and 5B). The picking up of relay 1L causes the energization of relay 1OC. The energization of the line circuit with positive polarity causes

the energization of the relays 1SO, 1SOS and 1FA. The picking up of relay 1FA causes the energization of relays 1SA and 1SB, and the picking up of relay 1SB causes the dropping away of relays 1L and 1RL. The detail of the circuits, which provide the above mode of operation, has been included in the description of the means provided for station selection.

The picking up of relay 1SB closes a circuit for the energization of relay 1VP from (+), through a circuit including front contact 155 of relay 1SB, front contact 156 of relay 1SO, front contact 157 of relay 1FA, wire 158, back contact 159 of relay V1 and winding of relay 1VP, to (-). The picking up of relay 1VP closes a stick circuit, for maintaining that relay energized while relay 1FA is dropping away, from (+), through a circuit including front contact 155 of relay 1SB, front contact 156 of relay 1SO, front contact 160 of relay 1VP, back contact 159 of relay V1, and winding of relay 1VP, to (-). The dropping away of relay 1FA at the end of the conditioning period closes a second stick circuit for relay 1VP, which maintains that relay energized after the first stepping relay is picked up, from (+), through a circuit including front contact 155 of relay 1SB, front contact 156 of relay 1SO, back contact 157 of relay 1FA, wire 161, front contact 162 of relay 1VP and winding of relay 1VP, to (-).

The dropping away of relay 1FA at the end of the conditioning period closes a circuit for energizing relay V1 from (+), through a circuit including front contact 163 of relay 1SB, front contact 164 of relay 1SO, back contact 165 of relay 1FA, wire 166, front contact 167 of relay 1VP, back contact 168 of relay V4, back contact 169 of relay V2, and winding of relay V1, to (-). The picking up of relay V1 closes a stick circuit for that relay from (+), through a circuit including front contact 170 of relay 1SB, wire 171, front contact 172 and winding of relay V1, to (-).

The picking up of relay 1FA during the next period of energization of the line circuit (first "on" period) causes the deenergization of relay 1VP by opening its circuit at back contact 157, the other stick circuit and the pick up circuit having been opened at back contact 159 by the picking up of relay V1.

The dropping away of relay 1FA, during the next period of deenergization of the line circuit (second "off" period) closes a circuit for the energization of relay V2 from (+), through a circuit including front contact 163 of relay 1SB, front contact 164 of relay 1SO, back contact 165 of relay 1FA, wire 166, back contact 167 of relay 1VP, back contact 173 of relay LV, back contact 174 of relay V3, front contact 175 of relay V1, and winding of relay V2, to (-). The picking up of relay V2 closes a stick circuit for that relay from (+), through a circuit including front contact 176 of relay V1, front contact 177 of relay V2, and winding of relay V2, to (-).

The picking up of relay 1FA, during the next period of energization of the line circuit (second "on" period) closes a circuit for the picking up of relay 1VP, from (+), through a circuit including front contact 155 of relay 1SB, front contact 156 of relay 1SO, front contact 157 of relay 1FA, wire 158, back contact 173 of relay V3, front contact 179 of relay V2, and winding of relay 1VP, to (-).

In a similar manner to the mode of operation described for the first two steps, and to the mode of operation described for the stepping relay bank

at the control office, the relay 1VP shifts its position during each "on" period in response to the picking up of relay 1FA, and one and only one stepping relay is picked up during each "off" period for as many steps as are provided.

The dropping away of relay 1FA at the end of the last "on" period closes a circuit for the energization of relay LV from (+), through a circuit including front contact 163 of relay 1SB, front contact 164 of relay 1SO, back contact 165 of relay 1FA, wire 166, front contact 167 of relay 1VP, front contact 168 of relay V4, and winding of relay LV, to (-). The picking up of relay LV closes a stick circuit for that relay from (+), through a circuit including front contact 180 of relay V4, front contact 181 of relay LV, and winding of relay LV, to (-).

The dropping away of relay 1FA also causes the successive dropping away of relays 1SA and 1SB by opening the circuit for relay 1SA at front contact 130. After relay 1SB has dropped away, the circuit for relay 1VP is opened at front contact 155, and the stick circuit for relay V1 is opened at front contact 170. The dropping away of relay V1 causes the dropping away of relays V2, V3, V4 and LV respectively in succession, due to each relay having its stick circuit opened by the relay for the preceding step.

The line circuit is again energized from the control office after sufficient time has been provided by the clearing out of the control office relays to insure the complete clearing out of the relays at the field stations. If the system is to enter a period of rest, a negative energization of the line circuit at the control office at the beginning of such period, causes the relay 1F to close polar contact 30 in a left hand position, and such operation causes the picking up of relay 1RL by closing the pick up circuit for that relay at that polar contact. The picking up of relay 1RL opens the stick circuit for relay 1OC at back contact 128 and causes that relay to be dropped away.

Thus, the field station steps in synchronism with the control office, the control office measures the length of the periods during a control cycle, including the conditioning and clearing out periods, and the field stations respond during each period with a sufficient margin of time at the end of that period to insure the complete operation at the field stations although those stations may lag the control office due to line circuit conditions and variations in battery voltage and individual relay characteristics.

55 *Reception of controls.*—Having described how controls are selected and transmitted from the control office, how the particular field station is selected for the reception of those controls, and how the stepping is accomplished, consideration is now given to the means provided at each of the field stations for the reception of control codes.

60 Assume, for example, that a control code is transmitted from the control office for the normal positioning of the track switch TS at the station nearest the control office. Under such conditions, the line circuit, during the fourth "on" period, is energized with positive polarity. Such energization, during the fourth "on" period, causes the positioning of the polar contacts of relay SMR (see Figs. 5A and 5B), by the energization of the upper winding of that relay by a circuit closed from (+), through a circuit including front contact 125 of relay 1SO, polar contact 30 of relay 1F in a right hand position,

wire 149, back contact 428 of relay LV, front contact 121 of relay V4, and upper winding of relay SMR, to (-). Such energization of relay SMR causes its polar contact 182, to assume a right hand position and apply energy to the normal control wire of the switch machine SM. It is to be understood that the control of the switch machine SM also includes locking means and overload protection in any well-known suitable manner.

If the polarity of the fourth impulse were negative, as is the case when lever SML in the control office (see Fig. 2), is in a right hand position, the polar contacts of relay 1F would assume a left hand position and close a circuit for the energization of lower winding of relay SMR, from (+), through a circuit including front contact 125 of relay 1SO, polar contact 39 of relay 1F in a left hand position, wire 147, back contact 429 of relay LV, front contact 31 of relay V4, and lower winding of relay SMR, to (-). Under such conditions, relay SMR operates its polar contacts to a left hand position and closes a circuit through contact 182 in a left hand position for energizing the reverse control wire of the switch machine SM.

In a similar manner, other controls are received, in accordance with the requirements of practice, during additional steps not shown.

Although the controls have been shown as being effective as soon as they are received, those controls can remain stored until the system has completed the stepping and then be executed all at one time. Such a mode of operation provides that the controls received become effective only if the stepping is properly completed. Thus, the controls received are ineffective in case of an under-step of the system due to an abnormal condition. The circuit for the execution of the controls can be closed, for example, through a circuit including a back contact of relay SA, at the field station receiving controls, and a front contact of the relay LV at that station.

Likewise, controls received are ineffective in case of an over-step due to abnormal conditions. The circuit for the execution of controls can include, for example, front contacts on the control code storage relays, which are automatically opened in case of an over-step.

The control code storage relays are released by the release of relay SO when an over-step occurs. By means of the following circuit arrangements the stick circuit for relay SO during the control portion of the cycle includes a back contact 148 of relay LV, as previously described. It has been pointed out that the relay LV picks up when relay FA releases following the last authorized "on" period. The pick up of relay LV opens the stick circuit for the SO relay that was established when the station was selected. Hence, relay SO will release if relay FA is again picked up as, for example, by an over-step. If relay FA picks up, due to an over-step, the stick circuit for relay 1SO will be opened at back contact 138 of relay 1FA.

Indications.—The transmission of indications from the field stations to the control office is rendered effective only from a period of rest. In other words, the line circuit must be energized with a negative polarity before an indication cycle can be initiated. During the transmission of indications the line circuit is energized at the control office and is impaled at the field station transmitting indications. Such impaling at the field station closes the line circuit to create an

"on" period and opens it to create an "off" period. The energization of the impaling relay E at the field station transmitting, is dependent upon the timing relays which determine the length of the time spaces and of the impulses.

At the control office detector relays are provided which are responsive to the length of the time spaces and of the impulses during an indication cycle. The position of each of the detector relays at the control office is stored by storing relays and is registered during the following period, step-by-step, so that the indications are registered on the control panel in the order in which they are received.

15 *Automatic start from a field station.*—A change in any of the conditions of the apparatus in the field that are to be indicated in the control office, interrupts the stick circuit for the relay CH at that station. For example, any change in the position of either or both of the relays T and M (see Fig. 5B), in the specific embodiment shown, interrupts the stick circuit for relay 1CH by a change in the position of either or both of contacts 26 and 25 respectively.

25 The dropping away of relay 1CH, for example, during or prior to a period of rest, closes a pick up circuit for relay 1CHP, provided the system is at rest, from (+), through a circuit including back contact 133 of relay 1OC, front contact 184 of relay 1RL, back contact 185 of relay 1L, back contact 186 of relay 1SB, back contact 187 of relay 1S, winding of relay 1CHP, wire 188, and back contact 189 of relay 1CH, to (-).

35 The picking up of relay 1CHP closes a stick circuit including front contact 190 for shunting back contact 189 of relay 1CH out of the control circuit. A stick circuit is also closed for relay 1CHP, for maintaining it picked up until the indications at that station are transmitted, from (+), through a circuit including back contact 266 of relay V4, code jumper 431, wire 267, front contact 268 of relay 1CHP, winding of relay 1CHP, front contact 190 of relay 1CHP, to (-).

40 45 Energy is applied to that stick circuit, during transmission of controls, at back contact 269 of relay 1S, which is picked up during an indication cycle only.

The picking up of relay 1CHP closes a circuit, 50 provided the line circuit is still energized with negative period of rest current, for the energization of relay 1LO from (+), through a circuit including back contact 191 of relay 1SB, back contact 192 of relay 1L, front contact 193 of relay 1RL, front contact 194 of relay 1CHP, and winding of relay 1LO, to (-). The picking up of relay 1LO opens the line circuit at back contact 146 and causes the dropping away of all of the relays F included in that line circuit.

60 65 When relay 1F drops away, the shunt circuit, that under normal conditions prevents the picking up of relay 1L, is removed by the opening of polar contact 30 of relay 1F in a left hand position, and causes the quick picking up of relay 1L. When relay 1L picks up, relay 1LO is dropped away by the opening of its circuit at back contact 192. Thus, each field station which has indications to transmit opens the line circuit for a short period of time, and then closes it up again.

70 At the control office (see Fig. 2) the dropping away of relay F due to the breaking of the line circuit, closes a circuit for the energization of relay CF from (+), through a circuit including back contact 50 of relay SC, back contact 51

of relay CDS, back contact 195 of relay F, front contact 196 of relay OR, and winding of relay CF, to (-), and the dropping away of relay F also opens the circuit by which relay NC is normally energized at front contact 14. When relay CF is picked up, a stick circuit is closed for maintaining it energized from (+), through a circuit including back contact 53 of relay SB, back contact 54 of relay C, front contact 271 of relay CF, and winding of relay CF, to (-). Relay SA picks up in the conditioning period prior to the picking up of relay SB and closes a circuit for maintaining relay CF energized throughout the indication cycle at front contact 55.

The picking up of relay CF closes a circuit for the energization of relay OC from (+), through a circuit including back contact 11 of relay SD, back contact 12 of relay C, front contact 13 of relay CF, and winding of relay OC, to (-). After relay SD is picked up, at the end of the conditioning period, a circuit is closed for energizing relay OC throughout the cycle of operation whenever relay F is dropped away, from (+), through a circuit including front contact 56 of relay OC, front contact 57 of relay SD, back contact 75 of relay F, and winding of relay OC, to (-). A circuit is also closed, upon the picking up of relay CF, for the energization of relay E (see Fig. 3) from (+), through a circuit including front contact 120 of relay CF, back contacts 114, 115, 116, 117 and 118 of relays LV, V4, V3, V2 and V1 respectively, back contact 119 of relay VP, and winding of relay E, to (-). The operation of relay E is repeated by the operation of relay EP which is energized, during an indication cycle only, when relay E is picked up, from (+), through a circuit including front contact 197 of relay CF, front contact 198 of relay E, and winding of relay EP, to (-).

After relay OC has picked up, relay NC is again picked up by the energization of a circuit (see Fig. 2) closed from (+), through a circuit including front contact 56 of relay OC, back contact 57 of relay SD, back contact 58 of relay C, front contact 65 of relay CF, and winding of relay NC, to (-). The picking up of relay SC, prior to the picking up of relay SD, maintains the circuit for relay NC closed at front contact 66 throughout the indication cycle.

When the line circuit is again energized by the picking up of relay NC, conditioning for the stepping takes place at both the control office and the field stations. The line circuit is closed under such conditions through the same circuit as heretofore described for a control cycle except that it includes front contact 270 of relay CF instead of front contact 76 of relay C. At the control office the picking up of relay F closes a circuit for relay FA (see Fig. 3) from (+), through a circuit including front contact 199 of relay CF, back contact 77 of relay PC, front contact 78 of relay F, and winding of relay FA, to (-). At the same time, a circuit is closed for the energization of relay SA by a circuit closed from (+), through a circuit including front contact 199 of relay CF, front contact 200 of relay F, and winding of relay SA, to (-), and a circuit is also closed at the same time for the energization of relay SC from (+), through a circuit including front contact 201 of relay CF, front contact 202 of relay F, and winding of relay SC, to (-).

The picking up of relay SA opens the stick circuit for relay OR (see Fig. 2) at back contact 28, and causes that relay to drop away because its pick up circuit is open at back contact 23 of relay

CF. Relay SB is also picked up by the energization of an obvious circuit closed upon the picking up of relay SA. The picking up of relay SC closes an obvious circuit for the picking up of relay SD and at the same time closes a circuit for the picking up of relay TOF which is used for detecting the long "off" periods, from (+), through a circuit including front contact 203 of relay CF, front contact 204 of relay SC, front contact 205 of relay F, and winding of relay TOF, to (-).

A circuit is closed by the picking up of relay SD for the energization of relay VP in the same manner as heretofore described when considering the operation of the stepping relay bank for the control office. The picking up of relay VP opens the circuit for relay E at front contact 119, and the dropping away of relay E closes a stick circuit for relay TOF from (+), through a circuit including front contact 203 of relay CF, back contact 206 of relay E, front contact 207 of relay TOF, and winding of relay TOF, to (-). The dropping away of the repeater relay EP closes the stick circuit for relay TOF through back contact 208 in multiple with back contact 206 of relay E.

At the field station, after the line circuit has been again energized at the control office by the picking up of relay NC, the picking up of relay 1F causes the picking up of relay 1FA by the energization of a circuit closed from (+), through a circuit including polar contact 129 of relay 1F in a left hand position, front contact 209 of relay 1L, and winding of relay 1FA, to (-). After relay 1FA is picked up, a circuit is closed for the energization of relay 1LOF from (+), through a circuit including jumper 1, back contacts 210, 211, 212 and 213 of relays V1, V2, V3 and V4 respectively, wire 260, back contact 214 of relay 1LO, front contact 215 of relay 1CHP, back contact 216 of relay 1SO, front contact 217 of relay 1FA and winding of relay 1LOF, to (-). The picking up of that relay closes a stick circuit from (+), through a circuit including front contact 218 of relay 1FA, front contact 219 of relay 1LOF, and winding of relay 1LOF, to (-). The picking up of relay 1LOF is of course dependent upon the position of the jumper 1, which, when in the dotted position, provides that the first "off" periods shall be short because of the failure of relay 1LOF to pick up.

At the same time relay 1S is energized by a circuit closed from (+), through a circuit including front contact 220 of relay 1FA, back contact 221 of relay 1SO, back contact 222 of relay 1LO, wire 223, back contact 224 of relay V1, wire 225, and winding of relay 1S, to (-). After relay 1S is picked up, relay 1SA is picked up by the energization of a circuit closed from (+), through a circuit including front contact 226 of relay 1S, front contact 227 of relay 1OC, and winding of relay 1SA, to (-). The picking up of relay 1SA closes an obvious circuit for relay 1SB including front contact 154.

When relay 1SB is picked up, the relays 1L and 1RL are dropped away because their circuit is opened at back contact 36, and a pick up circuit is closed for relay VP in the same manner as has heretofore been described except that the circuit includes front contact 228 of relay 1CHP instead of front contact 156 of relay 1SO.

Relay 1CH is also picked up at this time by the energization of a circuit closed from (+), through a circuit including front contact 229 of relay 1SB, front contact 230 of relay 1CHP, wire

231, back contact 430 of relay V1, and upper winding of relay 1CH, to (—). After relay 1CH has been picked up, its stick circuit remains closed until another change occurs in the position of the devices to be indicated.

The closing of front contacts 232 and 233 of relays 1SA and 1SB respectively, provide energization for relay 1FA as a direct repeater of relay 1F throughout the indication cycle.

The picking up of relay 1VP under the above conditions causes relay 1LO to pick up again by the closing of a circuit from (+), through a circuit including front contact 234 of relay 1VP, wire 235, back contact 236 of relay 1SO, front contact 237 of relay 1S, front contact 194 of relay 1CHP, and winding of relay 1LO, to (—). A stick circuit is closed after relay 1LO is picked up from (+), through a circuit including front contact 181 of relay 1SB, front contact 238 of relay 1LO, and winding of relay 1LO, to (—). The closing of the stick circuit provides that the relay 1LO is maintained picked up throughout the indication cycle. The picking up of relay 1LO opens the line circuit at back contact 146 to mark the end of the conditioning period and also to lock out all more distant stations by maintaining that part of the line circuit open which includes those stations.

Indication codes.—The indication codes consist of long and short periods. Each period, consisting of one "off" or one "on" period, can be either long or short. The number of different codes provided by a particular number of periods is equal to two raised to the power of the number of periods used for the station registration code. In order that stations can be identified in the control office, a different station registration code is assigned to each station. The station illustrated is shown as having a station registration code composed of three characters transmitted on three successive periods. Three periods provide a capacity of eight stations. Additional periods are used for station registration when required.

The period following those periods used for station identification is used for registering at the control office the identity of the particular station transmitting. Such a period is conveniently predetermined to be "long" at all stations by the position of the code jumpers at those stations.

The number of remaining steps necessary for the transmission of indications depends upon the number of indications to be provided. As an example of how the indications are transmitted, the position of the signal repeater relay M has been shown to have its indication transmitted on the third "off" period, and the position of the track relay T has been shown to have its indication transmitted on the third "on" period.

In order that the indication cycles may be as short as possible, the position of the apparatus to be indicated most frequently is indicated by a short period, whereby the indication cycles on an average consist of a greater number of short than long periods.

Transmission of indication codes.—After the relay LO has been picked up to mark the end of the conditioning period for an indication cycle and to sectionalize the line circuit as described above, the field station conditioned nearest the control office is set into operation to transmit its registration code. If the first "off" period of the registration code is to be long, the timing

relay LOF at that station is picked up during the conditioning period in accordance with the position of a code jumper. If the first "off" period is to be short, the circuit for relay LOF is not closed by that code jumper. If the first "on" period of the registration code is to be long, the timing relay LON at that station is picked up during the preceding "off" period in accordance with the position of a code jumper. If the first "on" period is to be short, the circuit for relay LON is not closed by that code jumper.

In a similar manner, the timing relay LOF is energized during each "on" period if the position of the code jumpers or the devices to be indicated defines that the next "off" period shall be long, and the timing relay LON is energized during each "off" period if the position of the code jumper or the device to be indicated defines that the next "on" period shall be long.

20 The relay E at the field station transmitting indication codes is controlled in a manner similar to the relay E at the control office, that is, it is energized after the picking up of a stepping relay during the "off" periods, and it is deenergized after the shifting of relay VP in the "on" periods. Its picking up is delayed, however, by relay LOF, if that relay has been energized during the preceding "on" period to effect a long "off" period, and its dropping away is delayed by relay LON, if that relay has been energized during the preceding "off" period.

To consider an example of the above described mode of operation, assume the station illustrated nearest the control office to transmit its station registration code which has been shown as being long, long, short, followed by a long to register its identity. It is also to be assumed that the relays T and M at that station remain in their normal positions shown to cause the third "off" and third "on" periods to be short.

30 The picking up of relay 1LO at the end of the conditioning period closes a circuit for relay 1LON from (+), through a circuit including jumper 2, back contact 239 of relay V2, back contact 240 of relay V4, front contact 241 of relay 1VP, wire 242, back contact 243 of relay 1E, front contact 244 of relay 1LO, and winding of relay 1LON, to (—). The picking up of relay 1LON closes a stick circuit, after relay 1FA has dropped away, from (+), through a circuit including back contact 245 of relay 1FA, front contact 246 of relay 1LON, front contact 244 of relay 1LO, and winding of relay 1LON, to (—).

40 The deenergization of the line relay 1F opens the circuit for relay 1FA at polar contact 129, and the dropping away of relay 1FA opens the stick circuit for relay 1LOF, at front contact 218, which starts the timing of relay 1LOF which is slow in dropping away.

50 The dropping away of relay 1FA also closes a circuit for the stepping relay V1 through the same circuit as heretofore described except that front contact 247 of relay 1LO is included in the circuit instead of front contact 164 of relay 1SO.

60 After relay 1LOF has completed its timing and dropped away, a circuit is closed for relay 1E from (+), through a circuit including front contact 248 of relay 1SB, wire 249, back contacts 250, 251 and 252 of relays V4, V3 and V2 respectively, front contact 253 of relay V1, front contact 254 of relay 1VP, wire 255, back contact 256 of relay 1LOF, front contact 257 of relay 1LO, and winding of relay 1E, to (—). The line circuit is closed by the picking up of relay 1E at front

contact 258 to mark the beginning of the first "on" period. A stick circuit is closed by the picking up of relay 1E at front contact 259 to shunt out back contact 256 of relay 1LOF so that relay 1LOF can be picked up during that "on" period if the next "off" period is to be long.

The picking up of relay 1FA at the beginning of the first "on" period causes the dropping away of relay 1VP in a manner heretofore described, and at the same time it starts the timing of relay 1LON which is slow in dropping away, by opening its stick circuit at back contact 245. The dropping away of relay 1LON causes relay 1E to drop away by opening its stick circuit at contact 263, the other stick circuit for relay 1E having been opened by the shifting of relay 1VP at front contact 254. The dropping away of relay 1E opens the line circuit at front contact 258 and marks the end of the first "on" period. Relay 1LOF is not energized during this period because the station registration code provides that the second "off" period is short. If the second "off" period were to have been long, jumper 3 would have been placed in the dotted position and relay 1LOF would have been picked up by the energization of a circuit closed from (+), through a circuit including jumper 3, front contact 210 of relay V1, back contacts 211, 212 and 213 of relays V2, V3 and V4 respectively, wire 260, front contact 214 of relay 1LO, front contact 261 of relay 1E and winding of relay 1LOF, to (-).

The dropping away of relay 1FA at the beginning of the second "off" period causes the energization of relay V2 in a manner heretofore described in detail. The picking up of relay V2 causes the picking up of relay 1E by the energization of a circuit closed from (+), through a circuit including front contact 248 of relay 1SB, wire 249, back contacts 250 and 251 of relays V4 and V3 respectively, front contact 252 of relay V2, back contact 254 of relay 1VP, wire 255, back contact 256 of relay 1LOF, front contact 257 of relay 1LO, and winding of relay 1E, to (-). The picking up of relay 1E closes the line circuit at front contact 258 and marks the end of the second "off" period. If the relay 1LOF had been picked up at the beginning of the first "on" period it would have started the timing when its stick circuit was opened by the dropping away of relay 1FA at front contact 218, and the picking up of relay 1E to close the line circuit would have been delayed until relay 1LOF had dropped away to close back contact 256. Relay 1LON is picked up during the second "off" period if jumper 4 is in the position shown to close a circuit for its energization from (+), through a circuit including jumper 4, front contact 262 of relay V1, back contact 442 of relay V3, back contact 241 of relay 1VP, wire 242, back contact 243 of relay 1E, front contact 244 of relay 1LO, and winding of relay 1LON, to (-), and a stick circuit is closed for relay 1LON at back contact 245 of relay 1FA to maintain that relay energized until relay 1FA is picked up at the beginning of the next "on" period.

The picking up of relay 1FA at the beginning of the second "on" period causes the picking up of relay 1VP in a manner heretofore described, and at the same time it starts the timing of relay 1LON by opening its stick circuit at back contact 245, and the dropping away of relay 1LON effects the dropping away of relay 1E by opening its stick circuit at front contact 263, because the other circuits for relay 1E are opened by the

picking up of relay 1VP at back contact 254. The dropping away of relay 1E opens the line circuit at front contact 258 and marks the end of the second "on" period. Relay 1LOF was not energized during the second "on" period because its circuit was open because of the picked up position of relay M to cause the next "off" period to be short. If the relay M had been in a dropped away position, under such conditions, a circuit would have been closed for energizing relay 1LOF when relay 1E picked up at the beginning of the second "on" period, by a circuit closed from (+), through a circuit including back contact 264 of relay M, front contact 211 of relay V2, back contacts 212 and 213 of relays V3 and V4 respectively, wire 260, front contact 214 of relay 1LO, front contact 261 of relay 1E, and winding of relay 1LOF, to (-). The picking up of relay 1LOF closes a stick circuit including front contact 218 of relay 1FA.

The dropping away of relay 1FA at the beginning of the third "off" period causes the energization of relay V3 in a manner heretofore described in detail. The picking up of relay V3 causes the picking up of relay 1E by the energization of a circuit closed from (+), through a circuit including front contact 248 of relay 1SB, wire 249, back contact 250 of relay V4, front contact 251 of relay V3, jumper 432, front contact 254 of relay 1VP, wire 255, back contact 256 of relay 1LOF, front contact 257 of relay 1LO, and winding of relay 1E, to (-). The picking up of relay 1E closes the line circuit at front contact 258 and marks the end of the third "off" period. If the relay 1LOF had been picked up at the beginning of the second "on" period, it would have started the timing of the third "off" period when a stick circuit was opened by the dropping away of relay 1FA, and the picking up of relay 1E to close the line circuit would have been delayed until relay 1LOF had dropped away to close back contact 256. Relay 1LON would be picked up during the third "off" period if relay T were dropped away to close a circuit for its energization from (+), through a circuit including back contact 265 of relay T, front contact 239 of relay V2, back contact 240 of relay V4, front contact 241 of relay 1VP, wire 242, back contact 243 of relay 1E, front contact 244 of relay 1LO, and winding of relay 1LON, to (-). The picking up of relay 1LON under such conditions would close a stick circuit as heretofore described. If relay T remains picked up, however, the pick up circuit for relay 1LON is open at back contact 265 to prevent its energization.

The picking up of relay 1FA at the beginning of the third "on" period causes the dropping away of relay 1VP in a manner heretofore described. Relay 1E is dropped away because its circuits are opened at front contact 254 of relay 1VP, and at back contact 263 of relay 1LON, the third "on" period having been selected as a short period by the picked up position of relay T. Relay 1E in dropping away opens the line circuit at front contact 258 to mark the end of the third "on" period. If relay 1LON had been picked up at the beginning of the third "on" period, it would have started the timing of the third "on" period when a stick circuit was opened by the picking up of relay 1FA, and the dropping away of relay 1E to open the line circuit would have been delayed until relay 1LON had dropped away to open the stick circuit for relay 1E at front contact 263.

Thus each of the third "on" and "off" periods

have had their length determined in accordance with the position of code jumpers and in accordance with devices to be indicated. If a greater number of devices are to be indicated than those shown, a proportionate number of selected periods and the necessary channels for transmission of those indications are provided. In any case, the system continues to transmit until all of the indications are transmitted, and then enters a clearing out period on the following step, irrespective of whether the following step is the last step as provided by relay LV, or whether that following step is any one of the other stepping relays. In other words, the length of each indication cycle is dependent upon the station transmitting. If the station transmitting has comparatively few indications to transmit, that indication cycle is comparatively short. If the station transmitting has a comparatively large number of indications to transmit, that indication cycle is comparatively long.

As an example of such termination of an indication cycle, assume the indications to be transmitted as described. Under such conditions, relay V4 is picked up as a result of the dropping away of relay 1FA during the fourth "off" period, but in picking up it does not close a circuit for relay 1E, as is done by the preceding stepping relays, because there is no jumper connecting front contact 250 of relay V4 and the heretofore described pick up circuit for relay 1E. Thus the system is cleared out because the line circuit is held open by relay 1E at front contact 253.

The picking up of relay V4, under such conditions, causes the dropping away of relay 1CHP by opening its stick circuit at back contact 260. Relay 1S is dropped away because its circuit is held open at front contact 220 of relay 1FA, and the dropping away of relay 1S opens the circuit for relay 1SA at front contact 226. Relay 1SB is deenergized by the dropping away of relay 1SA, and its dropping away opens the stick circuit for relay V1 at front contact 170, which causes the successive dropping away of relays V2, V3 and V4 respectively. When the line circuit is again closed at the control office, after the control office equipment has cleared out, the normal-at-rest condition of the system is provided in the same manner described for the end of a control cycle, provided there are no stored starts in the control office.

To consider an example of how the indication cycle is terminated when each of the indication channels available is used, assume additional indications to be provided for the station illustrated in Figs. 5A and 5B to be transmitted during the fourth "off" and the fourth "on" periods. Under such conditions, jumper 445 is associated with front contact 250 of relay V4, and the jumper 431 is associated with back contact 433 of relay LV instead of with back contact 266 of relay V4. Thus the stick circuit for relay 1CHP is closed at back contact 433 of relay LV instead of at back contact 266 of relay V4, and relay 1E can be energized after relay V4 is picked up in the fourth "off" period, and when relay 1LOF is in a dropped away position, by a circuit closed from (+), through a circuit including front contact 248 of relay 1SB, wire 249, front contact 250 of relay V4, jumper 445, back contact 254 of relay 1VP, wire 255, back contact 256 of relay 1LOF, front contact 257 of relay 1LO, and winding of relay 1E, to (-). The picking up of that relay closes the line circuit at front contact 258 to mark the beginning of the fourth "on" period.

The picking up of relay 1VP during that fourth "on" period opens the circuit for relay 1E at back contact 254 to cause its release immediately if that "on" period is to be short, and to be released upon the dropping away of relay 1LOF if that "on" period is to be long. The opening of the line circuit at front contact 258 of relay 1E causes the dropping away of relays F and FA to initiate the clearing out of the system in a similar manner to that heretofore described for an indication cycle of a shorter length, except that relay 1CHP is maintained energized until relay LV is picked up to open back contact 433, and except that relay LV is dropped away after the preceding stepping relays have been released.

Reception and registration of indication codes.—After considering how long and short "off" and "on" periods are effected by the field station transmitting, in accordance with registration and indication codes, consideration is now given to the means provided at the control office for receiving and registering such codes.

As has been pointed out, the field station marks the beginning and the end of each impulse of an indication cycle to determine its length. Thus, at the control office, in order to detect the difference between long and short impulses a detector relay TON is provided which has time to drop away during a long "on" period, but which, under ideal conditions, is never deenergized as long as the "on" periods are short during the transmission of indications. Such a means for measuring the length of the period depends entirely upon the dropping away time of a series of quick acting relays which have comparatively constant drop away characteristics. If the impulse is made long at the field station, the relay TON has plenty of time to drop away to detect a long "on" period.

It is desirable, however, because the conditions encountered in practice are not always ideal, to provide further insurance for the maintaining of relay TON picked up as long as the "on" periods are short by the shunting of the winding of that relay with a resistance to make it a little slower in dropping away. Conditions which could require such slow action could be, for example, variable line circuit conditions or variable battery voltage conditions.

In a similar manner a detector relay TOF is provided which is energized so long as short "off" periods are received but which is dropped away during each long "off" period. The winding of that relay is also shunted by a resistance to provide that it is a little slow in dropping away to compensate for variable conditions, such as line and battery conditions.

In response to the dropping away of relay TON during an indication cycle, a storing relay LON is picked up to store the condition of relay TON until it can be executed in the following "off" period. In response to the dropping away of relay TOF during an indication cycle, a storing relay LOF is picked up to store the condition of relay TOF until it can be executed during the following "on" period. Such an arrangement provides that relays TON and TOF can be picked up while their prior position is being executed, thus causing no delay in the operation of the system due to the execution of indications received.

As an example of how long and short impulses and long and short time spaces are received at the control office in accordance with indication codes transmitted from a field station, assume

the station illustrated in Figs. 5A and 5B to transmit its registration code.

The first "off" period, according to that registration code, is long. When the line circuit is opened at the end of the conditioning period at the field station, the dropping away of relay F (see Fig. 3) at the control office causes the dropping away of relay FA. The dropping away of relay F also causes the picking up of relay TON by the energization of a circuit closed from (+), through a circuit including front contact 203 of relay CF, front contact 204 of relay SC, back contact 205 of relay F, and winding of relay TON, to (-).

When relay FA is dropped away, the first of the stepping relays, V1, is picked up, and the picking up of that relay causes the picking up of relay E, all as has already been described when considering the stepping and impulsing. The picking up of relay E closes a circuit for its repeater relay EP. A stick circuit is closed for relay TON by the picking up of relay E, from (+), through a circuit including front contact 203 of relay CF, front contact 206 of relay E, front contact 272 of relay TON, and winding of relay TON, to (-), and the picking up of relay EP closes front contact 208 as a shunt for front contact 206 of relay E.

The picking up of relay EP opens the stick circuit for relay TOF, which was picked up during the conditioning period, at back contact 208, and causes the dropping away of that relay because its pick up circuit is open at that time at front contact 205 of relay F. The dropping away of relay TOF closes a pick up circuit for relay LOF from (+), through a circuit including front contact 203 of relay CF, front contact 273 of relay SD, back contact 274 of relay TOF, and winding of relay LOF, to (-); and the picking up of that relay closes a stick circuit from (+), through a circuit including front contact 203 of relay CF, front contact 275 of relay EP, front contact 276 of relay LOF, and winding of relay LOF, to (-).

There has been time for all of these relay operations because the first "off" period has been made long at the field station. If, however, that time period is made short by the field station, relay TOF remains energized because its stick circuit remains closed at back contact 208 of relay EP until its pick up circuit is again closed by the picking up of relay F at the beginning of the next "on" period. Under such conditions, when the "off" period is short, relay LOF remains in a dropped away position.

The energization of the line circuit at the beginning of the first "on" period causes the picking up of relay F, which in turn closes the pick up circuit for relay TOF at front contact 205. The picking up of relay F also closes a circuit for the pilot relay POF1 (see Fig. 4) from (B+), through a circuit including front contact 271 of relay LOF, front contact 278 of relay CF, front contact 279 of relay F, front contact 280 of relay E, back contacts 281, 282 and 283 of relays V4, V3 and V2 respectively, front contact 284 of relay V1, and lower winding of relay POF1, to (B-). After that relay is picked up, it is maintained energized until the end of the cycle by a stick circuit closed from (+), through a circuit including front contact 285 of relay SC, front contact 286 of relay POF1, and upper winding of relay POF1, to (-).

The picking up of relay FA causes relay VP to be dropped away, which causes the dropping away of relay E as described when considering the detail of the stepping and impulsing at the

control office. The dropping away of relay EP opens the circuit for relay LOF, at front contact 275 which causes that relay to drop away because its pick up circuit is open at back contact 274 of relay TOF.

The dropping away of relay EP opens the stick circuit for relay TON at front contact 208, and that relay drops away because its pick up circuit is held open at back contact 205 of relay F by the long impulse transmitted from the field station during that period. If the field station makes that impulse short, as is the case at some stations, relay TON does not become deenergized because its pick up circuit is closed at back contact 205 of relay F before its stick circuit is opened at front contact 208 of relay EP.

The dropping away of relay TON, during the first "on" period, causes the picking up of relay LON by the energization of a circuit closed from (+), through a circuit including front contact 203 of relay CF, front contact 273 of relay SD, back contact 287 of relay TON, and winding of relay LON, to (-). The picking up of relay LON closes a stick circuit for that relay from (+), through a circuit including front contact 203 of relay CF, back contact 275 of relay EP, front contact 288 of relay LON, and winding of relay LON, to (-).

During the second "off" period, according to the conditions assumed, the dropping away of relay FA causes the picking up of relays V2, E and EP in turn as heretofore described. The picking up of relay EP opens the stick circuit for relay TOF, but that relay does not drop away because its pick up circuit is closed by the picking up of relay F at the beginning of the next "on" period. If the field station effects a long second "off" period, the relay TOF drops away because its stick circuit is opened prior to the closing of its pick up circuit.

The dropping away of relay F at the beginning of the second "off" period, closes a circuit for the pilot relay PON1 (see Fig. 4), from (B+), through a circuit including front contact 289 of relay LON, front contact 290 of relay CF, back contact 291 of relay F, back contact 292 of relay E, back contact 293 of relay VP, back contact 294 of relay V3, front contact 295 of relay V1, and lower winding of relay PON1, to (B-). After that relay has picked up, it is maintained energized until the end of the cycle by a stick circuit closed from (+), through a circuit including front contact 285 of relay SC, front contact 296 of relay PON1, and upper winding of relay PON1, to (-). The picking up of relay EP during this period opens the circuit for relay LON at back contact 275 which causes that relay to drop away because its pick up circuit is open at back contact 287 of relay TON at that time. The long second "on" period is detected in the same manner as described for the first "on" period. Because the second "off" period was short, the circuit for pilot relay POF2 is open at front contact 271 of relay LOF (see Fig. 4) to prevent that relay from picking up.

During the third "off" period, which is short, if signal repeater relay M at the field station (see Fig. 5B), is picked up, and which is long if relay M at the field station is dropped away, the registration execution relay RX is picked up by the energization of a circuit closed from (B+), through a circuit including front contact 289 of relay LON, front contact 290 of relay CF, back contact 291 of relay F, back contact 292 of relay E, front contact 293 of relay VP, back contact 297

of relay V4, front contact 293 of relay V2, and lower winding of relay RX, to (B-). The picking up of relay RX closes a stick circuit for that relay, from (+), through a circuit including front contact 285 of relay SC, front contact 299 of relay RX, and upper winding of relay RX, to (-).

The picking up of relay RX picks up relay ST by energization of a circuit extending from (+), through a circuit including front contact 301 of relay RX, front contact 302 of relay PON1, front contact 303 of relay POF1, back contact 304 of relay POF2, and winding of relay ST, to (-). Thus the identity of the calling station has been registered by the picking up of a particular station relay at the control office.

It is obvious that the long and short impulses and time spaces of the indication code are detected by the relays TON and TOF in the same manner as described for the registration code, and that those indications are registered during the following period. For example, if the third "off" period is short, a circuit is closed during the third "on" period by the picking up of relay F for the energization of polar relay ROF from (B-), through a circuit including back contact 277 of relay LOF, front contact 278 of relay CF, front contact 279 of relay F, front contact 280 of relay E, back contact 281 of relay V4, front contact 282 of relay V3, front contact 305 of relay ST, and winding of relay ROF, to (CN). Such energization causes that relay to operate its polar contact 306 to a left hand position to indicate that the signal is at stop. If the third "off" period is long, relay LOF is picked up to apply (B+) to the circuit just described, at front contact 277, and cause the polar contact 306 to be operated to a right hand position to indicate that the signal is clear.

During the last "off" period, the position of the track relay T at the field station is registered at the control office. If the track relay T is picked up, the third "on" period is short to cause a circuit to be closed upon the dropping away of relay F at the end of the last "off" period from (B-), through a circuit including back contact 289 of relay LON, front contact 290 of relay CF, back contact 291 of relay F, back contact 292 of relay E, back contact 293 of relay VP, front contact 294 of relay V3, front contact 307 of relay ST, and winding of relay RON, to (CN). If the third "on" period is long, that circuit at the beginning of the last "off" period is energized with the opposite polarity when (B+) is applied to front contact 289 of relay LON. The operation of the polar contact 308 in accordance with the polarity of relay RON, is used for controlling the track indicator lamp OS in an obvious manner.

The above described "off" period has been described as the last "off" period in accordance with the transmission of indications from the station as illustrated in Figs. 5A and 5B. If, however, more indications are provided at that station than those illustrated, to cause the stepping to be completed during an indication cycle, the above mentioned last "off" period becomes a fourth "off" period, and it is followed by a fourth "on" period.

In either event, the end of the last "on" period of an indication cycle causes the dropping away of relays F and FA at the control office to clear out the system. As a result of the dropping away of relay FA, relay LV is picked up (only if the stepping is completed) and relay SA is caused to drop away. When relay SA is dropped away, the stick circuit for relay CF is opened at front contact 55 (see Fig. 2) to cause that relay to drop away

and open the circuits for relays TON and TOF at front contact 203 (see Fig. 3). Relays SB, SC and SD drop away in succession as a result of the dropping of relay SA. The dropping away of relay SC causes the release of the stepping relays as heretofore described for a control cycle, and it also causes the release of the pilot relays POF and PON together with the registration execution relay RX, by opening their stick circuits at front contact 285 (see Fig. 4). The dropping away of relay RX causes the release of relay ST by opening its circuit at front contact 301. In response to the dropping away of relay SD, relay NC is picked up, if there are no stored starts at the control office, to cause the system to enter a period of rest as heretofore described. If there are stored starts at the control office, relay PC is picked up as heretofore described when considering the transmission during successive cycles of operation.

Lockout of field stations when control office transmits.—The quick acting relay L, provided for each of the field stations (see Figs. 1A and 1B), is picked up as soon as the control office opens the line circuit at the beginning of a control cycle, and the picking up of that relay opens the pick up circuit for relay LO at that station to prevent its energization to start an indication cycle; for example, the picking up of relay 1L opens the pick up circuit for relay 1LO at back contact 192. The picking up of relay SB at each location opens the circuit for relays L and RL, and the dropping away of relay RL holds the pick up circuit for the relay LO at that location open throughout the indication cycle because relay RL can be again picked up only during a period of rest. The picking up of relay 1SB, for example, opens the stick circuit for relay 1RL at back contact 36, and the dropping away of relay 1RL opens the pick up circuit for relay 1LO at front contact 193.

Relays SA and SB at each field station are maintained picked up throughout each control cycle to provide the above lockout features. Relay 1SA, for example, is maintained picked up during each control cycle, after relay 1SO has dropped away, by the energization during the "on" periods of a circuit closed from (+), through a circuit including front contact 130 of relay 1FA, back contact 131 of relay 1SO, back contact 408 of relay 1LO, wire 409, front contact 410 of relay Vt, wire 411, and winding of relay 1SA, to (-).

Lockout of control office when a field station transmits.—When a field station has initiated an indication cycle by causing a line break, the field control relay CF (see Fig. 1A), is picked up at the control office. The picking up of that relay opens the circuit for relay C, which is used to start a control cycle, at back contact 52. The relay CF is maintained picked up by a stick circuit throughout each indication cycle and thus prevents a control office start to become effective during that time.

Superiority of control office starts over field station starts.—It has been pointed out how the control office can store starts by the picking up of the relay CH at the control office for that start, and how each start becomes effective for transmission in a predetermined order, defined by the order in which the contacts of the relay CH appear in the pick up circuit for the relays CD.

It has also been pointed out how the relay CHP at each field station can be picked up to store field station starts until that station has a chance to transmit. The field station starts are limited; however, by the provision that they can

become effective only when a permission (—) polarity is applied to the line circuit, for example, when relay CHP is picked up (see Fig. 1B), it can become effective to energize relay LO, which opens the line circuit at back contact 146 to initiate an indication cycle, only when the line circuit is energized with negative polarity during a period of rest to provide the shunt circuit for relay L closed with polar contact 30 of relay F in the left hand position. If this shunt circuit is not closed during the period between cycles, relay RL is not picked up to close the pick up circuit for relay LO at front contact 193 of relay RL.

A reason for such a permission polarity in order to initiate a field start is to provide a means by which the control office can gain and maintain the control of the line circuit at the end of any cycle. Thus, while the control office apparatus is clearing out at the end of either an indication or a control cycle, the polarity for the energization of the line circuit for the following period is selected. If there are stored starts at the control office, it is determined that the next energization of the line circuit shall be positive, and if there are no stored starts at the control office, it is determined that the next energization of the line circuit shall be negative.

If the polarity of the line circuit, under such conditions is positive, the system immediately enters a conditioning period for a control cycle. If the polarity of the line circuit is negative, under such conditions, the system enters a period of rest from which either the control office or the field station can initiate a cycle of operation.

To consider an example of such a mode of operation, assume a control office start to be stored by the picked up position of relay CH (see Fig. 2), at the end of a cycle of operation which can be either an indication or a control cycle. The relays SA, SB, SC and SD at the control office drop away during either of such clearout periods successively in the order named, as has been heretofore described.

The dropping away of relay SC, under such conditions, closes a circuit at back contact 41 for the picking up of relay CD. The picking up of relay CD closes a stick circuit for that relay including the winding of relay CDS. The picking up of relay CDS closes a circuit for relay C at front contact 51 and opens the circuit for relay CF at back contact 51. The picking up of relay CF upon the dropping away of relay SC is prevented by front contact 196 of relay OR which is in the dropped away position at that time. When relay C is picked up, the energization of the relay NC is prevented by the opening of back contact 12.

After the stepping relays have dropped away, due to their stick circuit having been opened at front contact 75 of relay SC (see Fig. 3), a circuit heretofore described is closed for the energization of relay E.

The dropping away of relay SD, after all of the above relay operations have taken place, closes a circuit for the energization of relay PC (see Fig. 2), from (+), through a circuit including front contact 56 of relay OC, back contact 57 of relay SD, front contact 58 of relay C, front contact 60 of relay E, back contacts 427, 61, 62, 63 and 64 of relays LV, V4, V3, V2 and V1 respectively, and winding of relay PC, to (—). The picking up of relay PC applies positive energy to the control line wire 10 to cause the polar contacts of the relays F at the field stations to

be operated to a right hand position. With the polar contacts of the relays F at the field stations in a right hand position, all of the field stations are conditioned for a control cycle in a manner which has been described.

Thus, whenever the control office has a stored start, which can be provided at any time, it is determined that the next cycle of operation shall be a control cycle.

It is provided that the permission (—) must not only be applied to the line circuit to initiate a field station start, but, in order to make the transmission of indications from that station effective, the line circuit must be energized during the conditioning period following the line break with negative polarity. This condition is provided in order to provide a means whereby the control office start can overrule a field station start, if both starts occur simultaneously, or nearly simultaneously.

In reviewing the operation during a field station start, the relay CH at the field station having indications to transmit is picked up and causes the picking up of relay LO, which opens the line circuit. The opening of the line circuit causes the picking up of relay L at that station, which opens that pick up circuit for relay LO to cause relay LO to drop away and again close the line circuit. If, at this point in the operation, the control office applies positive energy to the line circuit, the operation of the polar contacts of relays F at the field stations to a right hand position causes the immediate picking up of the relay SO at each of the stations. The picking up of relay SO opens the second pick up circuit for the sectionalizing relay LO at that station and also prevents the picking up of relay S, which has a front contact included in the second pick up circuit for relay LO.

Consider, for example, a line break to be effected by relay LO (see Figs. 5A and 5B). The energization of the line circuit at the end of the break with positive polarity closes a circuit for the energization of relay ISO at polar contact 30 of relay F in a right hand position. The picking up of relay ISO opens the pick up circuit for relay LO at back contact 236, the other (or initial) pick-up circuit for relay LO being opened at back contact 192. Relay ISO remains energized on each control cycle at least during the conditioning and the first "off" periods so it opens the circuit for relay IS at back contact 221. With relay IS dropped away, the second pick up circuit for relay LO is open at front contact 237. The relay IS cannot be picked up after the relay VI has been picked up on the first "off" period opening its back contact 224, because the relay LO cannot be picked up to close its front contact 222 by reason of the open front contacts 237 and 193 of relays IS and RL respectively. Thus, the dropping away of relay ISO and the closure of its contact 221 during a control cycle in which this station fails to be selected, cannot effect the picking up of relay IS.

Consideration is now given to the means whereby the control office can cause the line circuit to be energized with positive polarity after a line break has been effected by a field station.

In reviewing the operation during a control office start, the relay CH picking up causes the successive picking up of relays CD, CDS and C. When the line break is effected by the field station in the event of a field start as described above, the dropping away of relay F at the control office closes a circuit for relay CF at back

contact 195, but if the relay CDS is picked up by a control office start, the circuit for relay CF is opened at back contact 51 of relay CDS to prevent its energization. If, however, relay CF is picked up prior to the picking up of relay CDS, the picking up of relay C is prevented by the opening of back contact 52. Thus it is provided that a control office start overrules a field station start if relay CDS is picked up prior to the picking up of relay CF, but if relay CF is picked up prior to the picking up of relay CDS, the field station gains control of the line circuit for that cycle.

The picking up of relay C, under the above conditions, causes the application of positive energy to the line circuit as has been described, and the picking up of relay CF, under the above conditions, causes the application of negative energy to the line circuit in a manner heretofore described.

Lockout between field stations.—When a field station transmits, the other field stations included in the system can be divided into two groups, one of which is composed of the stations more distant from the station transmitting (conveniently called remote stations) and the other of which is composed of stations between the field station transmitting and the control office (conveniently called intermediate stations).

It is possible that a number of stations can have indications to transmit at the same time. Under such conditions, each of those stations is conditioned as if it were to be the transmitter. Each of those stations picks up its sectionalizing relay LO at the end of the conditioning period and opens the line circuit for more remote stations. At the end of the first "off" period, the relay E is picked up at each of those remote stations to close the line circuit and mark the beginning of the first "on" period. The line circuit, however, becomes energized only in the section included between the control office and the nearest station that has sectionalized the line circuit. Thus each of the more remote stations is cleared out by the clearout relays S, SA, and SB. Relay OC at each of the remote stations remains energized until a period of rest is reached, for purposes hereinafter described.

The intermediate stations, after the line break, are conditioned in a manner similar to the station that is transmitting, except that their VP and stepping relays are not operated because relays CHP at those stations are in a dropped away position. The relays S and OC at each of those intermediate stations are maintained picked up during the impulsing, and relay S causes the energization of the relays SA and SB at each of those stations through circuits closed as has already been described.

If a change takes place at a field station after the line break has become effective, the relay LO at that station cannot be picked up to effect a second line break. The picking up of the relay L at that station opens the first pick up circuit for relay LO; for example, the picking up of relay 1L (see Fig. 1B), opens the pick up circuit for relay 1LO at back contact 192. After relay 1SB is picked up, that pick up circuit for relay 1LO is again opened at front contact 193 of relay 1RL until the system enters a period of rest. The second pick up circuit for relay 1LO remains open, when that station is an intermediate station, throughout the cycle at front contact 234 of relay 1VP.

Relay 1CHP is dependent, in its pick up cir-

cuit, upon the closing of back contact 185 of relay 1L; thus relay 1CHP can be picked up only prior to the picking up of relay 1L as a result of a line break. If relay 1CHP is picked up, but relay 1LO does not have a chance to pick up to initiate a line break, (because of such initiation having taken place at another station) that station is conditioned to transmit indications, because the pick up circuit for relay 1VP is closed at front contact 226 of relay 1CHP. The picking up of relay 1VP, under such conditions, causes relay 1LO to pick up and sectionalize the line circuit. Thus, once a cycle of operation is initiated by a line break, for either a control or an indication cycle, all other starts for the field stations are suppressed as soon as the quick acting relays L for those stations are picked up.

Distribution of indication cycles.—It has been pointed out that when a number of field locations 20 initiate simultaneous field starts, the station which is nearest the control office is eventually allowed to be the transmitter, and more remote stations are ruled out. If the nearer stations are allowed to transmit successive indication cycles, 25 the more remote stations, under certain conditions encountered in practice, rarely have an opportunity to transmit. Provision is made, in accordance with this invention, that consecutive indication cycles must be distributed among the various stations having stored starts, in such a manner that each station can transmit but one cycle in that series of cycles of operation.

Furthermore, the particular stations to transmit during a series of cycles is determined by the 30 stored starts at the beginning of that series, irrespective of the stored starts occurring while the series of indication cycles is being transmitted. Thus all field starts which have been effected after the beginning of a series of cycles are included in a second series, which can be initiated only after the system has been in a period of rest long enough to allow the special clearout relay OC at each station to drop away.

As has been pointed out, the initiation of an 45 indication cycle is dependent upon the picking up of relay CHP at that station. The relay CHP is dependent in its pick up circuit upon the dropped away position of relay OC at that station. For example, relay 1CHP (see Fig. 6), can 50 be picked up only when back contact 123 of relay 1OC is closed.

The dropping away of relay OC at the field station at the end of a cycle of operation, which 55 can be either a control or an indication cycle, is dependent upon its deenergization by the picking up of relay RL due to the normal energization of the line circuit, and upon its slow drop away characteristics. Such a mode of operation provides that relay OC at each of the field stations is maintained picked up throughout a series of consecutive cycles of operation. It will be noted that relay OC remains picked up at more remote stations during an indication cycle, after other clearout relays have been dropped away, by its stick circuit which is closed, for example, as is shown for relay 1OC, from (+), through a circuit including back contact 134 of relay 1FA, front contact 135 of relay 1OC, back contact 128 of relay 1RL, and winding of relay 1OC, to (-).

Such control for the relay CHP and the relay OC at each field station provides that one and only one indication cycle is transmitted from each field station having its relay CHP picked up at the beginning of the series, until the system has reached a period of rest for a time long

enough to allow the relays OC to drop away. All stations having changes to initiate starts occurring during a series can have their relays CHP picked up for effecting a start only at the beginning of the next series of cycles, after sufficient time is provided for relays OC to drop away.

A modified form of the system, relative to the distribution of indication cycles between field stations, is shown in Fig. 7, by which each station has a chance to transmit one cycle and one cycle only during a series, irrespective of when the change relay CH for that station was dropped away to initiate a start.

Under such conditions, a relay DS is provided for each station. That relay is so controlled that it is picked up only at the field station transmitting, and is maintained in a picked up position until a period of rest is reached for a period of time long enough to drop away relays OC which are controlled as heretofore described. A back contact of relay DS is included in the pick up circuit of relay CHP at that station to allow the picking up of that relay CHP only after a prolonged period of rest, or only if that station has not yet transmitted during a series of successive cycles of operation.

Relay IDS, for example, is picked up, when the station with which it is associated is transmitting, by the energization of a circuit closed from (+), through a circuit including front contact 309 of relay IOC, front contact 310 of relay V2, and winding of relay IDS, to (-). The picking up of relay IDS closes a stick circuit for that relay, because relay OC is picked up at that time, from (+), through a circuit including front contact 311 of relay IOC, front contact 312 of relay IDS, and winding of relay IDS, to (-).

When a change occurs to drop relay ICH, a pick up circuit is closed for relay ICHP, provided the line circuit is energized negative at the end of a preceding cycle of operation, from (+), through a circuit including front contact 313 of relay IRL, back contact 314 of relay IL, back contact 315 of relay ISB, back contact 316 of relay IDS, winding of relay ICHP, and back contact 317 of relay ICH, to (-). The picking up of that relay closes a stick circuit at front contact 318 for the negative side of the winding of that relay, and the stick circuit for the positive side of the winding is closed from (+), through a circuit including back contact 319 of relay V4, jumper 441, front contact 320 of relay ICHP, winding of relay ICHP, and front contact 318 of relay ICHP, to (-). The stick circuits for relay ICHP are maintained by back contact 321 of relay IS throughout a control cycle, but the circuit is opened at the end of an indication cycle to cause relay ICHP to drop away at back contact 319 of relay V4. The above stick circuit is provided in accordance with the system as shown in Figs. 5A and 5B, that is, provision is made for terminating the indication cycle after the third "on" period. If, however, there are more indications to be transmitted than those shown, jumper 441 is so located as to maintain relay CHP picked up until all of the indications have been transmitted.

Although many more indications can be transmitted during one cycle of operation than those illustrated, it may happen that a greater number of track switches and other traffic controlling devices are located and grouped at certain points along the system than can be adequately indicated by a single field station equipment during one cycle of operation as heretofore described.

To provide such additional indication facilities at such points or field locations, the traffic controlling devices at such field locations are divided into groups, with the system so organized as to transmit the indications associated with any particular group during a single cycle of operation, as well as a distinctive station registration code by which it is identified at the control office. Thus, each group at such a location is registered at the control office as a separate station, as if each group constituted a single station as illustrated in Figs. 5A and 5B, although it is unnecessary to provide each group with all of the apparatus illustrated in Figs. 5A and 5B because much of the equipment is common to every such group. For example, the field station equipment of Figs. 5A and 5B together with Fig. 8, provides for two groups of indications at a field location.

For the consideration of the feature of cycle distribution in connection with a larger number of indications at one point along the system than is transmitted by field station equipments at other points, it becomes convenient to refer to such a point as a field location having a plurality of indication stations.

It is also to be understood that in a much similar manner a greater number of controls for devices located and grouped at certain points along the system than can be adequately received by a single field station equipment during one cycle of operation, can be divided into groups, with the system so organized as to communicate controls to any one particular group during a single cycle of operation. Each group at such a location is selected by a separate station code, as if each group constituted a single station as illustrated in Figs. 5A and 5B, although it is unnecessary to provide each group with all of the apparatus illustrated in Figs. 5A and 5B because much of the equipment is common to every such group. Under such conditions, each of the groups is conveniently referred to as a control station.

To consider how a plurality of indication stations use common equipment, assume the field location illustrated in Figs. 5A and 5B to have two indication stations as shown in Fig. 8. Under such conditions (see Figs. 8 and 5B) wire 434 is connected to the back point of contact 210 of relay V1 instead of the wire shown connected to that point, wire 435 is connected to the back point of contact 239 of relay V2 instead of the wire shown connected to that point, wire 436 is connected to the front point of contact 210 of relay V1 instead of the wire shown connected to that point, wire 437 is connected to the front point of contact 211 of relay V2 instead of the wire shown connected to that point, wire 438 is connected to the front point of contact 239 of relay V2 instead of the wire shown connected to that point, and wire 439 is connected to the front point of contact 212 of relay V3.

Wires 434, 435 and 436 are connected to a particular group of registration code jumpers when that group is selected by the picking up of an LC relay. Wires 437, 438 and 439 are connected to a particular group of indication devices when that group is selected by the picking up of an LC relay. The wire connecting indication registration jumper 4 (see Fig. 5B) to the front point of contact 262 of relay V1 is maintained as shown because for this disclosure the second "on" period must always be long for an indication cycle in order to pick up relay RX at the control office.

Under the above assumed conditions the relays !OC , !RL , !L , !LO , !S , !SA , !SB , V4 , LV , !CH and !CH2 , shown in Fig. 8 in block form, are controlled by circuits shown in detail for relays of a similar character in Figs. 5A and 5B.

The circuits for the control of relay !CHP shown in Fig. 8 are provided in accordance with the system for the distribution of successive indication cycles between stations. The system shown in Fig. 8 provides the same mode of operation of the system as described in the main part of the disclosure, and as shown in Fig. 6, except that when the particular field location having a plurality of indication stations is allowed to transmit, during a series of cycles, one and only one cycle is transmitted for each indication station having a stored start at that location.

The relay !CHP (see Fig. 8) has its pick up circuit controlled in the same manner heretofore described in the main part of the disclosure except that front contact 322 of relay !LCS , is substituted for back contact 189 of relay !CH . Due to the fact that indication cycles are transmitted only so long as relay !CHP remains picked up, and due to the fact that relay !CHP can be picked up only when the system has entered a prolonged period of rest, the length of time during which relay !CHP is maintained by its stick circuit determines the number of indication cycles to be transmitted from that particular location. Thus it is provided at such field locations that each indication station has an opportunity to transmit one and only one indication cycle during a series of cycles of operation when that field location can have control of the line circuit.

Assume, for example, the relay !CH (see Fig. 8) to drop away as a result of a change in the position of the devices to be indicated for that indication station. Such a change closes a pick up circuit for relay !LC from (+), through a circuit including back contact 323 of relay !SB , back contact 324 of relay !LCS , back contact 325 of relay !CHL , back contact 326 of relay !CH , and upper winding of relay !LC , to (-). The opening of front contact 326 of relay !CH prevents the picking up of any other LC relays. The picking up of relay !LC closes a stick circuit for that relay, which also energizes relay !LCS , from (+), through a circuit including back contacts 327, 328 and 329 of relays !SA , !LO and LV , respectively, connected in multiple, winding of relay !LCS , front contact 330 of relay !LC and lower winding of relay !LC , to (-). Back contact 329 of relay LV opens that stick circuit at the end of a cycle; back contact 327 of relay !SA provides that stick energy is available when another LC relay is picked up; and back contact 328 of relay !LO maintains the stick circuit energized during control cycles, thus contacts 327, 328 and 329 cooperate to maintain stick circuit energy except for a moment at the end of an indication cycle during which a particular LC relay was permitted to gain control of the line.

In accordance with the system provided by this invention for determining the length of an indication cycle by the number of steps used in transmitting indications, it is assumed that one of the two indication stations requires all available channels for the transmission of indications. Thus, jumper 440 in Fig. 8 is shown connecting back contact 329 of relay LV to the stick circuit of the LC relays. To correspond with such conditions, jumper 445 in Fig. 5 is needed to connect front contact 250 of relay V4 to the

circuit for relay !E . Jumper 440 (see Fig. 8) assumes a position determined by the indication station having the greatest number of indications to transmit.

5 The picking up of relay !LCS opens the pick up circuit for relays LC at back contact 324. The picking up of relay !LC causes the picking up of relay !CHL by the energization of a circuit closed by the picking up of relay !CHP , from (+), through a circuit including front contact 330 of relay !CHP , front contact 331 of relay !LCS , front contact 332 of relay !LC , and winding of relay !CHL , to (-). A stick circuit is closed for relay !CHL when that relay picks up, 10 from (+), through a circuit including front contact 330 of relay !CHP , front contact 333 of relay !CHL , and winding of relay !CHL , to (-). Stick energy is applied for relay !CHP throughout an indication cycle by front contact 334 of relay !LCS , through an obvious circuit.

15 If a change occurs at one of the other stations at that field location while relay !CHP is picked up, such, for example, as to cause the dropping away of relay !CH2 , another stick circuit is closed for relay !CHP . If relay !CH2 is dropped away under such conditions, a stick circuit is closed for relay !CHP from (+), through a circuit including back contact 335 of relay !CH2 , back contact 336 of relay !CHL2 , front contact 268 of relay !CHP , winding of relay !CHP , and front contact 190 of relay !CHP , to (-). Such a circuit provides that relay !CHP is maintained picked up while relay !LCS is dropped away and again picked up at the end 20 of the cycle used for transmission of indications for the first station described. Relay !CHL2 is not picked up, to open front contact 336 of the stick circuit for relay !CHP until the indication cycle initiated by the dropping away of relay !CH has been transmitted. Relay !CHL2 is prevented from picking up, under such conditions, by the opening of back contact 324 of relay !LCS which prevents the picking up of relay !LC2 to close the pick up circuit for relay !CHL2 .

25 At the end of the indication cycle initiated by relay !CH , the relays !LCS and !LC drop away when their circuit is opened at back contact 329 of relay LV . The dropping away of relay !SB causes the picking up of relay !LCS , because the change relay !CH2 is in a dropped away position, by the energization of a circuit for the picking up of relay !LC2 , closed from (+), through a circuit including back contact 323 of relay !SB , back contact 324 of relay !LCS , front contact 325 of relay !CHL , back contact 337 of relay !CHL2 , back contact 338 of relay !CH2 , and upper winding of relay !LC2 , to (-). The picking up of relay !LC2 closes a stick circuit for that relay from (+), through a circuit including back contact 327 of relay !SA , winding of relay !LCS , front contact 339 of relay !LC2 , and lower winding of relay !LC2 , to (-).

30 Relay !LCS in picking up again applies stick energy to relay !CHP at front contact 334 as heretofore described. The picking up of relay !LCS also closes a pick up circuit for relay !CHL2 from (+), through a circuit including front contact 330 of relay !CHP , front contact 331 of relay !LCS , front contact 340 of relay !LC2 , and winding of relay !CHL2 , to (-), and the picking up of that relay closes a stick circuit from (+), through a circuit including front contact 330 of relay !CHP , front contact 341 of relay !CHL2 , and winding of relay !CHL2 , to (-).

35 When relay !CHL2 is picked up, under such

conditions, the stick circuit for relay 1CHP is opened at back contact 336 of relay 1CH2 to allow that relay to drop away when its other stick circuit is opened at the end of the indication cycle at front contact 334 of relay 1LCS.

In a similar manner relays CH, CHL and LC are provided for each of as many stations as are required at a particular field location, and those relays are controlled in a similar manner to the controls for the relays shown in Fig. 8.

Thus it has been illustrated and described that as long as any station at a particular field location has indications to transmit, a stick circuit is maintained for relay CHP at that location, provided that station has not yet transmitted since the last prolonged period of rest. It is obvious from the drawing and the detailed description that the relay LC nearest in the circuit to the source of energy is given preference over any LC relay more remotely located from that source.

Repeater station, general.—When a coded-centralized traffic controlling system extends from a control office over a considerable distance to a most remote field station, it is of a particular advantage to provide a repeater station at an intermediate point in order that the line circuit can be sectionalized to reduce the effect of line capacity and to reduce the voltage drop due to line resistance. Another use of a repeater station is to provide an efficient means for tying the line circuit for a branch of the system into the main line circuit.

With reference to Fig. 9, a repeater station is illustrated as having been provided for tying a branch line circuit into a main line circuit, and the circuits of the repeater station are such that it can be included in the main line circuit between any of the particular field stations or between the control office and the nearest field station. Thus, Fig. 9 can be considered between Figs. 1A and 1B, between Figs. 3 and 5A, or at the right of Fig. 5B.

The field stations included in the repeater line circuit have a similar mode of operation and they are controlled in the same manner as the field stations for the main line circuit, of which one station has been illustrated in Figs. 5A and 5B and described in detail.

The repeater station acts as a transmitter during both a control and an indication cycle. During a control cycle it transmits to the repeater line circuit the impulsing applied to the main line circuit, and during an indication cycle it transmits to the main line circuit the impulses of the repeater line circuit. Further description of the repeater station is now considered as to the details of the mode of operation.

Normal conditions at repeater station.—The main line circuit is normally energized, as heretofore described, with negative energy applied to the control line wire 10 at the control office. In accordance with such energization the polar contacts of the main line relay 3F (see Fig. 9) are in a left hand position to close a circuit for the energization of relay 3RL from (+), through a circuit including polar contact 342 of relay 3F in a left hand position, back contact 343 of relay 3L, back contact 344 of relay 3SB, and winding of relay 3RL, to (-). A stick circuit is also closed for that relay from (+), through a circuit including back contact 345 of relay 3SB, winding of relay 3L, front contact 346 of relay 3RL, and winding of relay 3RL, to (-). The pick-up circuit for relay 3RL shunts the stick circuit for that relay to cause relay 3L to remain in a dropped away position.

Relay 3NC is maintained energized with a comparatively low degree of energization by a stick circuit closed from (+), through a circuit including back contact 347 of relay 3SB, back contact 348 of relay 3L, back contact 349 of relay 3C, front contact 350 of relay 3F2, back contact 351 of relay 3CF, resistance 3R, front contact 358 of relay 3NC, and winding of relay 3NC, to (-).

The repeater line circuit is energized, under normal conditions, by a circuit closed from the negative terminal of battery 3CB, through a circuit including back contact 359 of relay 3PC, front contact 360 of relay 3NC, control line wire 361, winding of relay F and a back contact of the relay LO at each field station included in the line circuit, return line wire 362, front contact 363 of relay 3NC, back contact 364 of relay 3PC, winding of relay 3F2, front contact 365 of relay 3F2, and resistance 3R2, to the positive terminal of the battery 3CB. Such energization is of a comparatively low degree because of the resistance 3R2.

Relay 3OR is normally energized, under normal at rest conditions, by a circuit closed from (+), through a circuit including back contact 366 of relay 3SA, back contact 367 of relay 3CF, back contact 368 of relay 3C, back contact 369 of relay 3PC, front contact 370 of relay 3F2, and winding of relay 3OR, to (-); and that relay is also maintained by its stick circuit which is closed from (+), through a circuit including back contact 366 of relay 3SA, front contact 371 of relay 3OR, and winding of relay 3OR, to (-).

Thus the repeater line circuit is energized at a low degree during a rest period, which conserves energy required for normal energization and also provides that the line relays will respond more quickly to the deenergization of the line circuit. The low degree of energization of relay 3NC has the same advantages.

Repeater station operation for transmitting controls.—Assume, for example, the control office to transmit a control cycle of operation which is initiated from a period of rest. Under such conditions, the opening of the line circuit at the control office to cause a reversal in the polarity of energization of the line circuit from negative energization to positive energization, causes the picking up of the quick acting relay 3L, because its shunt circuit is opened at polar contact 342 of relay 3F when that relay is deenergized.

The picking up of relay 3L closes a circuit for the energization of relay 3OC from (+), through a circuit including back contact 347 of relay 3SB, front contact 348 of relay 3L, front contact 372 of relay 3RL, and winding of relay 3OC, to (-).

Relay 3OC is maintained picked up throughout a control cycle by energization of a stick circuit closed during each "off" period from (+), through a circuit including front contact 373 of relay 3OC, back contact 374 of relay 3FA, back contact 372 of relay 3RL, and winding of relay 3OC, to (-). The picking up of relay 3L causes the dropping away of relay 3NC by opening a circuit for that relay at back contact 348. The dropping away of relay 3NC opens the repeater line circuit at front contacts 363 and 360 to cause the deenergization of the repeater line circuit and the dropping away of the relays F (not shown) included in that circuit.

When the line circuit is again energized with positive potential at the control office, a circuit is closed for the energization of relay 3PC from (+), through a circuit including back contact 375 of relay 3SB, polar contact 376 of relay 3F,

in a right hand position, and winding of relay 3PC, to (-). The picking up of that relay closes the repeater line circuit for positive energization from the positive terminal of battery 3CB, through a circuit including front contact 377 of relay 3L, winding of relay 3F2, front contact 364 of relay 3PC, back contact 360 of relay 3NC, control line wire 381, winding of the relay F (not shown) at each field station included in the repeater line circuit, a back contact of the LO relay (not shown) for each station included in the repeater line circuit, return line wire 362, back contact 363 of relay 3NC, and front contact 359 of relay 3PC, to the negative terminal of battery 3CB.

Relay 3FA is picked up by the energization of an obvious circuit closed at polar contact 342 of relay 3F in a right hand position. The picking up of relay 3PC closes a pick up circuit for relay 3C from (+), through a circuit including back contact 378 of relay 3SB, front contact 379 of relay 3PC, and winding of relay 3C, to (-). Relay 3C is maintained picked up throughout the control cycle by the energization of a stick circuit closed after relay 3SA is picked up during the conditioning period, from (+), through a circuit including front contact 380 of relay 3SA, front contact 381 of relay 3C, and winding of relay 3C, to (-).

When relay 3C is picked up, a circuit is closed for energizing the relay 3SA from (+), through a circuit including front contact 382 of relay 3FA, front contact 383 of relay 3C, and winding of relay 3SA, to (-). The picking up of relay 3SA closes an obvious circuit to cause the picking up of relay 3SB. Relays 3SA and 3SB are slow acting clearout relays which remain picked up throughout an entire cycle of operation the same as described for the control office and for the field stations, the picking up of relay 3SA opens the circuit for relay 3OR at back contact 366 to cause that relay to drop away and remain in a dropped away position until the repeater line circuit is again energized for a period of rest. The picking up of relay 3SB opens the circuit for relays 3L and 3RL at back contact 345 to cause those relays to drop away and remain in a dropped away position until relay 3RL is again energized during a period of rest.

Thus the repeater station has been completely conditioned for a control cycle, and has applied positive energization to the control line wire of the repeater line circuit for conditioning the field stations. After the control office has completed its conditioning period, which allows sufficient time for the repeater station and the field stations to be conditioned, it opens the main line circuit to cause the deenergization of the line relays to mark the end of the conditioning period and the beginning of the first "off" period.

Under such conditions, at the repeater station, the relay 3PC is dropped away by the opening of its circuit at polar contact 376 of relay 3F, and the dropping away of that relay opens the repeater line circuit at front contacts 359 and 364. Thus the repeater line relays are dropped away as a result of the dropping away of the line relays for the main line circuit.

At the end of the first "off" period the control office applies energy of a selected polarity to the main line circuit, which causes the application of similar polarity to the repeater line circuit. Assume, for example, the control office to apply positive energization to the control line wire 10 to cause the relay 3F at the repeater station to oper-

ate its polar contact 376 to a right hand position. Under such conditions, a circuit is closed for relay 3PC from (+), through a circuit including front contact 384 of relay 3C, polar contact 376 of relay 3F in a right hand position and relay 3PC, to (-). The picking up of relay 3PC causes the positive energization of the control line wire 361 by the closing of front contacts 359 and 364. If the control office applies negative polarity to the control line wire 10, under such conditions, the polar contacts of relay 3F are operated to a left hand position to close a circuit for the energization of relay 3NC from (+), through a circuit including front contact 384 of relay 3C, polar contact 376 of relay 3F in a left hand position, back contact 385 of relay 3OR, and winding of relay 3NC, to (-). Each time the repeater line circuit is closed during a control cycle, after the picking up of relay 3C, that circuit includes front contact 386 of relay 3C instead of front contact 371 of relay 3L, as heretofore described for the energization of the line circuit at the beginning of the conditioning period.

In a similar manner for each step the repeater line circuit is energized with a selected polarity in accordance with the energization of the main line circuit, and is deenergized each time that the main line circuit is deenergized. Such impulsion of the repeater line circuit of course causes the same mode of operation for each of the field stations included in that line circuit as has been described for the particular field station shown in detail in Figs. 5A and 5B.

When the line circuit is deenergized at the control office at the beginning of a clearing out period, at the end of a control cycle, the dropping away of relay 3F at the repeater station opens the circuit for relay 3FA at polar contact 342 and opens the circuit for relays 3PC and 3NC at polar contacts 376. The dropping away of relay 3FA opens the circuit for relay 3SA at front contact 382 and the dropping away of relay 3SA opens the circuit for relay 3SB to cause that relay to drop away. The dropping away of relay 3SA causes the dropping away of relay 3C by opening its circuit at front contact 380.

In response to the dropping away of relay 3PC or 3NC, depending upon which one was picked up during the last "on" period, the repeater line circuit is deenergized to mark the beginning of the clearing out period for each of the field stations included in that line circuit, and to cause the dropping away of relay 3F2 at the repeater station.

Thus, the clearing out at the repeater station is completed, and after the control office has completely cleared out, it applies energy to the line circuit to mark either the beginning of a rest period or the beginning of a control cycle. Assume the control office to enter a period of rest and apply negative polarity to the line wire 10 to cause relay 3F to operate its polar contacts to a left hand position. Such energization closes a circuit for relay 3NC from (+), through a circuit including back contact 375 of relay 3SB, polar contact 376 of relay 3F in a left hand position, back contact 385 of relay 3OR, and winding of relay 3NC, to (-). At the same time a normal pick up circuit heretofore described for relay 3RL is closed at polar contact 342 of relay 3F in a left hand position. The picking up of relay 3RL opens the stick circuit for the slow release relay 3OC at back contact 372 to cause that relay to drop away if the system remains in a prolonged period of rest.

The picking up of relay 3NC at the beginning of a period of rest closes a circuit for the energization of the repeater line circuit from the negative terminal of battery 3CB through a circuit including back contact 359 of relay 3PC, front contact 360 of relay 3NC, control line wire 361, winding of relay F at each field station, back contact of relay LO at each field station, return line wire 362, front contact 363 of relay 3NC, back contact 364 of relay 3PC, winding of relay 3F2, and back contact 381 of relay 3OR, to the positive terminal of battery 3CB. As soon as relay 3F2 is picked up, the pick up circuit heretofore described for relay 3OR is closed at front contact 370, and the picking up of that relay opens the pick up circuit for the line relays at back contact 381 to provide for the normal at rest low degree of energization of the line circuit, including the resistor 3R2 as heretofore described.

Repeater station operation for transmitting indications.—When a field station included in the repeater line circuit transmits indications, a relay 3E is used at the repeater station to repeat in the main line circuit the long and short impulses effected in the repeater line circuit. It is necessary at the repeater station to provide lockout means for the more remote stations included in the main line circuit, under such conditions. Such a lockout arrangement is provided by means of the lock-out relay 3LO similar to the lockout means provided at each of the field stations.

Assume, for example, a field station included in the repeater line circuit to transmit an indication cycle from that station to the control office. The opening of the repeater line circuit at that field station to register a field start, causes the dropping away of relay 3F2 which, when dropped away, closes a circuit for the field control relay 3CF, from (+), through a circuit including back contact 347 of relay 3SB, back contact 348 of relay 3L, back contact 349 of relay 3C, back contact 350 of relay 3F2, front contact 388 of relay 3OR, and winding of relay 3CF, to (-). The stick circuit is closed, when relay 3CF is picked up, from (+), through a circuit including back contact 389 of relay 3SB, back contact 381 of relay 3C, front contact 390 of relay 3CF, and winding of relay 3CF, to (-). When relay 3SA picks up later in the conditioning period, the stick circuit is provided with energy at front contact 389 for maintaining relay 3CF picked up throughout the indication cycle.

The dropping away of relay 3F2 opens the circuit by which relay 3NC is normally energized at front contact 350 and causes that relay to be dropped away. The picking up of relay 3CF closes a pick up circuit for relay 3LO from (+), through a circuit including back contact 391 of relay 3SB, back contact 392 of relay 3L, front contact 393 of relay 3CF, and winding of relay 3LO, to (-).

The picking up of relay 3LO under such conditions opens the main line circuit at back contact 394 to cause the dropping away of the relay F at the control office and at the locations in the main line circuit for starting the conditioning of the control office equipment for the indication cycle. The opening of the line circuit under such conditions causes the picking up of relay 3L when its shunt circuit is opened at polar contact 342 of relay 3F, and the picking up of relay 3L opens the pick up circuit for relay 3LO at back contact 392 to cause that relay to drop

away and again close the main line circuit at back contact 394.

5 The picking up of relay 3L also provides a pick up circuit for relay 3OC closed from (+), through a circuit including back contact 347 of relay 3SB, front contact 348 of relay 3L, front contact 372 of relay 3RL, and winding of relay 3OC, to (-). Relay 3OC is maintained by a stick circuit throughout the cycle of operation in the same manner as above described in considering the operation during a control cycle.

10 After the control office has again applied energy to the main line circuit to mark the end of the line break period for that circuit, the operation of the polar contacts of relay 3F to a left hand position closes a circuit for relay 3FA from (+), through a circuit including polar contact 342 of relay 3F in a left hand position, front contact 343 of relay 3L, and winding of relay 3FA, to (-). When relay 3FA is picked up, a circuit is closed for relay 3S, from (+), through a circuit including front contact 382 of relay 3FA, back contact 383 of relay 3C, and winding of relay 3S, to (-).

20 25 When relay 3S is picked up, a circuit is closed for the energization of relay 3NC from (+), through a circuit including back contact 384 of relay 3C, front contact 395 of relay 3CF, front contact 396 of relay 3OC, front contact 397 of relay 3S, and winding of relay 3NC, to (-). The picking up of relay 3NC closes the line circuit at front contacts 363 and 360 to cause its energization with negative polarity throughout the indication cycle. Such a circuit is the same as heretofore described during a control cycle except that front contact 398 of relay 3CF is included in the circuit instead of front contact 386 of relay 3C. With the line circuit energized as described, the field station included in the repeater line circuit which has indications to transmit is conditioned, during negative energization of the line circuit, in a similar manner to the conditioning described for a station included in the main line circuit.

35 40 45 When relay 3S is picked up, a circuit is closed for the energization of relay 3SA, from (+), through a circuit including front contact 399 of relay 3OC, front contact 400 of relay 3S, and winding of relay 3SA, to (-). When that relay is picked up an obvious circuit is closed for the picking up of relay 3SB and the circuit for relay 3OR is opened at back contact 366 in the same manner as heretofore described. When relay 3SB is picked up, a circuit is closed to cause the picking up of relay 3E, by the energization of a circuit closed from (+), through a circuit including front contact 347 of relay 3SB, back contact 401 of relay 3C, front contact 402 of relay 3F2, and winding of relay 3E, to (-). Relay E opens and closes the main line circuit at front contact 403 after the main line circuit has become sectionalized by the picking up of relay 3LO. After relay 3E has picked up, the picking up of relay 3LO is again effected by the energization of the pick up circuit closed from (+), through a circuit including front contact 391 of relay 3SB, front contact 404 of relay 3E, back contact 405 of relay 3C, front contact 393 of relay 3CF, and winding of relay 3LO, to (-). A stick circuit is closed upon the picking up of relay 3LO, from (+), through a circuit including front contact 366 of relay 3SA, front contact 406 of relay 3LO, and winding of relay 3LO, to (-). Relay 3LO in picking up opens the main line circuit at

50 55 60 65 70 75 back contact 394 and immediately closes it again

at front contact 394, because relay E is picked up to close the circuit at front contact 403. Thus the main line circuit is sectionalized to drop out more remote stations, and it is energized between the repeater station and the control office until the repeater line circuit has been opened at the field station transmitting to mark the end of the conditioning period.

After the repeater line circuit has been opened at the end of the conditioning period by the picking up of the relay LO at the field station transmitting, the relay 3F2 at the repeater station is dropped away, and it causes the dropping away of relay 3E by opening its circuit at front contact 402. The dropping away of relay 3E opens the main line circuit at front contact 403 to cause the dropping away of the relays F included therein. Relay 3FA acts as a quick acting repeater of relay 3F throughout the cycle of operation during which its pick up circuit is closed at front contact 407 of relay 3SA.

At the end of the first "off" period, the closing of the repeater line circuit by the field station transmitting causes the picking up of relay 3F2 which closes the pick up circuit for relay 3E at front contact 402. The picking up of relay 3E closes the main line circuit at front contact 403 to cause the picking up of the relay F at the control office.

Thus it is obvious that the transmitting relay 3E operates as a repeater of the line circuit relay 3F2 which is included in the repeater line circuit, and that it opens and closes the main line circuit in accordance with the impulsion of the repeater line circuit by the field station transmitting.

Having considered how the impulses are transmitted to the control office for the stepping, consideration can be now given to the manner in which the repeater station is cleared out at the end of the impulsion. When the repeater line relay 3F2 is dropped away at the end of the last "on" period, relay 3E is dropped away by the opening of front contact 402 and its dropping away opens the main line circuit at front contact 403 to initiate the clearing out at the control office. Relay 3F is dropped away, together with its associate repeater relay 3FA, and the dropping away of relay 3FA opens the circuit for relay 3S at front contact 382 to cause that relay to drop away and open the circuit for relay 3SA at front contact 400. Relay 3SA causes the dropping away of relay 3CF by opening its stick circuit at front contact 380, and it also causes the dropping away of relay 3LO by opening its stick circuit at front contact 366. It also causes the dropping away of relay 3SB. When relay 3S is dropped away, relay 3NC drops away because its circuit is opened at front contact 397.

The control office marks the end of the clearing-out period and the beginning of a rest period (in the same manner as has heretofore been described) in which the line circuit is energized with negative polarity to cause the polar contacts of relay 3F to be operated to a left hand position. Such operation closes a pick up circuit for relay 3NC from (+), through a circuit including back contact 375 of relay 3SB, polar contact 376 of relay 3F in a left hand position, back contact 385 of relay 3OR, and winding of relay 3NC, to (-). Relay 3RL is also picked up by the energization of a circuit closed from (+), through a circuit including polar contact 342 of relay 3F in a left hand position, back contact 343 of relay 3L, back contact 344 of relay 3SB, and winding of relay 3RL, to (-).

The picking up of relay 3NC closes a circuit for the energization of the repeater line circuit with full potential at front contacts 363 and 360 because the line circuit is closed at back contact 387 of relay 3OR. After relay 3F2 has picked up, due to such energization of the line circuit, the pick up circuit for relay 3OR is closed at front contact 370 to cause that relay to pick up and open the pick up circuit for the relays F included in the repeater line circuit at back contact 387 to cause those relays to be maintained energized by the normal circuit closed through the limiting resistor 3R2. The relay 3OC is deenergized upon the picking up of relay 3RL and is dropped away because its circuit is opened at back contact 372 of relay 3RL. The line circuit conditions heretofore described as normal have thus been restored, and the repeater station is again in condition to be used for repeating the transmission of either a control or an indication cycle of operation.

In case of starts at comparatively simultaneous times, between the control office and a field station included in the repeater line circuit, the control office is given control of the line circuit in much the same manner as has been described. If the polarity of the line circuit is reversed in the control office prior to the picking up of relay 3CF, relay 3PC at the repeater station is picked up by the energization of an obvious circuit including polar contact 376 in a right hand position. The picking up of that relay causes the picking up of relay 3C by the energization of a circuit heretofore described. When relay 3C is picked up, the pick up and stick circuits for relay 3CF are opened at back contact 381 to prevent the picking up of that relay, or to cause it to drop away if it is already picked up. When relay 3PC is picked up at the repeater station, the repeater line circuit is energized with positive polarity in order to condition the field stations included in the repeater line circuit for a control cycle. Such energization overrules the indication cycle start initiated at any of the field stations included in that repeater line circuit.

Support for clearout relays during long "on" and long "off" periods.—It has been pointed out that the system clears out in the event of an abnormally long "on" or "off" period. If there is an abnormally long "on" period, the relay OC at the control office, at the repeater station, and at each field station is dropped away to clear out the system. If there is an abnormally long "off" period, the relay SA and its repeater relays are dropped away to clear out the system at the control office, at the repeater station, and at each of the field stations.

In order to insure the maintaining of the clearout relays picked up during long "on" and long "off" periods used in transmitting indications, additional support is provided for each of the types of clearout relays under such conditions.

During a long "off" period, the clearout relay SA at each of the intermediate field stations is maintained picked up by the relay S at that station. The relays S may be dropped away during a long "off" period without affecting the operation of the system, but the relays SA associated with the S relays do not have time to drop away. In other words, there is not time during a long "off" period of normal length for both of the slow release relays S and SA to drop away.

At the control office, the relay SA is energized, during the first part of a long "off" period by a circuit (see Fig. 3) closed from (+), through a

circuit including front contact 412 of relay E, front contact 413 of relay TOF, and winding of relay SA, to (-). Such energization provides that relay SA does not have time to drop away during a long "off" period of normal length, but will drop away if that long "off" period is abnormally long.

At the repeater station, a relay 3S is provided to support the relay 3SA in the same manner described for supporting the relays SA at the field stations.

During a long "on" period, the clearout relay OC at each of the intermediate field stations is maintained picked up, by the additional support provided by relay LON at that station. Relay 1LON, for example, is picked up during "off" periods of an indication cycle, when that station is an intermediate station, by the energization of a circuit closed from (+), through a circuit including back contact 245 of relay 1FA, front contact 414 of relay 1SB, back contact 415 of relay 1SO, back contact 244 of relay 1LO, and winding of relay 1LON, to (-). When relay 1LON is picked up, under such conditions, relay IOC is energized by a circuit closed from (-), through a circuit including front contact 416 of relay 1LON, front contact 135 of relay 1OC, back contact 128 of relay 1RL, and winding of relay 1OC, to (-). Due to the slow dropping away characteristics of relays 1LON and 1OC, although relay 1LON may drop away during a long "on" period of normal length, there is not sufficient time during such a period for both slow acting relays to drop away.

At the control office, the relay OC is energized during a part of a long "on" period by a circuit (see Fig. 2) closed from (+), through a circuit including front contact 56 of relay OC, front contact 51 of relay SD, front contact 417 of relay TON, back contact 418 of relay E, and winding of relay OC, to (-). Such energization provides that relay OC does not drop away during a long "on" period of normal length, but will drop away if the long "on" period is abnormally long.

At the repeater station the relay 3OC is supported, during a long "on" period by relay 3FB. Relay 3FB is picked up during the "off" periods by the energization of a circuit closed from (+), through a circuit including back contact 382 of relay 3FA, front contact 419 of relay 3SB, and winding of relay 3FB, to (-). That relay is maintained picked up during the first part of each "on" period because it is not deenergized until relay 3FA is picked up to open its circuit at back contact 382, and because the winding of that relay is shunted by a resistance 3R3 to make it slow in dropping away. When relay 3FB is picked up, relay 3OC is energized by a circuit closed from (+), through a circuit including front contact 373 of relay 3OC, front contact 420 of relay 3FB, back contact 372 of relay 3RL, and winding of relay 3OC, to (-). Relay 3OC is not dropped away during a long "on" period of normal length, because there is not sufficient time during such a period for relays 3FB and 3OC to both drop away, but relay 3OC is dropped away if the long "on" period is abnormally long.

Line drainage.—An electrostatic charge is built up between the line wires when they are energized. Such an electrostatic charge will remain for a considerable time if the line circuit is opened at the far end and then disconnected from the source of energy. Under these conditions, if, while the energy was still disconnected,

the line should be closed at the far end, the electrostatic charge would flow through the line wires and line relay windings to the point at which the line is closed at the far end. Under certain conditions, particularly if the line wires have a long length and are associated with a large value of inter-wire capacity, the discharge of such a line will be of sufficient intensity to momentarily operate some of the line relays in the line circuit. 5 The line relay at the far end of the line circuit would be most affected by the discharge current. 10 A momentary pick up of one or more line relays, in the manner described, and more particularly the momentary pick up of the line relay at a remote location attempting to initiate an indication cycle 15 would be troublesome.

The line relay at the remote location should not pick up until and unless energy from the control office line battery is impressed upon the 20 line wires at the control office. Line drainage is used to avoid the unauthorized momentary pick up of a remote line relay should the remote location close the end of the line before energy was applied at the control office, as would be the case 25 if the LO relay at the remote location dropped away and closed its back contact 146 before the relays PC or NC had picked up to reapply energy to the line after a line break at the beginning of a cycle.

30 Line drainage is accomplished at the control office by means of a circuit extending from line wire 19 through back contact 421 of relay PC, resistor R4, back contact 422 of relay NC to return line wire 18. This circuit provides a path

35 as soon as the PC and NC relays are both down and energy thus removed from the line to permit the electrostatic charge to escape through resistance R4 which limits the rate at which the charge is permitted to escape and thus withdraw the

40 charge from the line without operating the line relays. As a result the electrostatic charge on the line will have been sufficiently reduced to prevent the unauthorized pick up of remote line relays should the line be closed at the remote location 45 prior to the time at which energy is again applied at the control office to mark the beginning of the conditioning period following a line break at the start of a cycle.

A similar arrangement is employed at a repeater station. In this case the drainage circuit 50 extends from line wire 361 through back contact 423 of relay 3PC, resistor 3R4, back contact 424 of relay 3NC, to return line wire 362. The operation of this drainage circuit is after the manner described for the control office.

55 Referring to Figs. 1A, 3 and 9 it will be noted that the drainage circuit described above is completed each time the line circuit is disconnected from the line battery CB. Therefore in addition to the line drainage provided at the beginning of 60 a cycle, as described above, line drainage is also provided during each "off" period of a control cycle. This operation is advantageous because the drainage path at the control office tends to increase the speed with which the energy in the line circuit will disappear and therefore release the line relays by providing a path at the control office for part of the energy to escape while the balance of the energy is being drained through

65 the remote end of the line circuit. The practical advantage of the drainage circuit under these conditions is to reduce the time lag between the operation of the remote line relays after battery energy is removed from the line circuit at the 70 control office.

If line circuit conditions exist whereby the line relay F at the receiving station tends to lag the line relay F at the transmitter, a resistance is shunted across the relay FA at the transmitter to cause that relay to be slow in dropping away in order to compensate for the lagging at the receiving end of the circuit. By adjusting the value of the resistance in accordance with the line circuit conditions, the proper drop away time for the relay FA at the transmitter is effected.

The use of such a resistance is so selected that it is effective for shunting only at the transmitter, for example, the resistance R3 (see Fig. 3) is effective for shunting relay FA only when the control office is transmitting and front contact 97 of relay C is closed. When one of the field stations transmits, the resistance R5 having a different value is effective for shunting relay FA in order to properly adjust the dropping away characteristic of that relay when the control office is receiving.

In a similar manner, at the field station illustrated in Figs. 5A and 5B, resistance 1R is shunted across relay 1FA when relay 1LO is picked up to close front contact 425, and a resistance 1R2, having a different value, provides different drop away characteristics for relay 1FA when front contact 426 of relay 1SO is closed during a control cycle.

Having described a particular centralized traffic controlling system as one specific embodiment of the present invention, it is desired to be understood that this form is selected to facilitate in the disclosure of the invention rather than to limit the number of forms which it may assume; and, it is to be further understood that various modifications, adaptations and alterations may be applied to the specific form shown to meet the requirements of practice, without in any manner departing from the spirit or scope of the present invention except as limited by the appending claims.

What we claim is:

1. In a code communication system for transmitting indications from a field station to a control office, a single line circuit connecting the control office and field station and including a source of energy in the control office, a line relay at the field station, step-by-step means at the field station operated in response to repeated operation of said line relay, an impulsing relay at the field station controlled by said step-by-step means at that station to be effective to alternately open and close said line circuit for each step to impress a series of time spaced impulses of normal lengths thereon, a normally deenergized impulse timer relay at the field station for when energized causing said impulsing relay to make an impulse of abnormal length, a pick-up circuit for said impulse timer relay closed or left open during each step in accordance with the indication to be transmitted during the impulse period for that step, a normally deenergized space timer relay for when energized to cause said impulsing relay to make a space period of abnormal length, and a pick-up circuit for said space timer relay closed or left open during each step in accordance with the indication to be transmitted during the space period for that step.

2. In a code communication system of the character described for a plurality of field stations, a single line circuit connecting the control office and the several field stations, manual start means at the control office, means in the control office for energizing said line circuit with one particular

polarity or the other dependent upon the non-operated or operated condition of said manual start means, cycle marking means at each station non-responsive in its inactive condition to the energization of said line circuit with said one particular polarity, electro-responsive stick relay means at each station responsive to a temporary opening of said line circuit and which if once active remaining active in spite of reenergization of said line circuit until said cycle marking means has responded for rendering said cycle marking means responsive to either polarity of energization of said line circuit, and field start means which responds when a new indication is to be transmitted to the office and effective only if said line circuit is then energized with current of said particular polarity for temporarily opening said line circuit.

3. In a communication system of the character described for transmitting controls from a control office to a field station and for transmitting indications from the field station to the control office; a line circuit connecting a control office and a field station and including a source of energy at the control office; transmitting means at the control office effective when initiated for energizing said line circuit with a series of impulses having selected polarities; means for energizing said line circuit with one particular polarity when said transmitting means is inactive; transmitting means at the field station effective when set into operation for causing the line circuit to be energized from said source of energy with relatively long and relatively short time spaced impulses only of said one particular polarity; initiating means at the control office for initiating said control office transmitting means and effective only after it has first energized said line circuit with current of the opposite polarity preceding each series of coded impulses transmitted from the control office; initiating means at the field station effective, only if said line circuit is energized with said one particular polarity for a predetermined time after having been momentarily deenergized by such initiating means, to set said field transmitting means into operation, whereby the transmitting means at the control office becomes superior to the transmitting means at the field station whenever both transmitting means are initiated at the same time because the office initiating means may remove said one polarity of current from said line circuit at any time during said predetermined time.

4. In a code communication system for a control office and a plurality of field stations; a single line circuit connecting the control office and field stations; cycle marking means in the control office and each field station including a slow-acting relay assuming its normal deenergized condition at the end of an operating cycle after a prolonged deenergization of said line circuit; manually operable starting means at the control office for initiating operation of the system for transmission of controls; means in the control office for energizing said line circuit with current of one polarity while the system is at rest, and responding to operation of said starting means prior to the energization of the slow-acting relay in said office to change the energization of said line circuit by energizing it with a current of the other polarity; equipment at each field station comprising, a changeable device having different conditions to be indicated in the control office, lockout means responding to a change in the con-

dition of said device and effective only if said line circuit is then energized with current of said particular polarity for temporarily opening said line circuit to create a field start condition in the control office; said lockout means acting to again open said line circuit to sectionalize said line circuit and terminate it at the corresponding station, said termination of the line circuit occurring after energization of said slow-acting relays, a stick circuit closed upon energization of said slow-acting relay for maintaining said lockout means in its operated condition before the ensuing operating cycle, and means responsive to the energization of said line circuit with current of said other polarity after the energization of said slow-acting relay for maintaining said lockout means in its operated condition before the ensuing operating cycle, and means responsive to the energization of said line circuit with current of said other polarity prior to the energization of said slow-acting relay for preventing a second operation of said lockout means.

5. In a two-wire code communicating system of the character described, a single line circuit connecting a control office and a plurality of field stations, a cycle marking slow-release relay at each field station assuming its inactive deenergized condition after a prolonged deenergization of said line circuit, said cycle marking relay after deenergization thereof being non-responsive to energization of said line circuit with current of a particular polarity, electro-responsive stick relay means at each field station responsive to a momentary opening of said line circuit after its energization with current of said particular polarity for when actuated rendering a subsequent energization of said line circuit by current of either polarity effective to energize said cycle marking relay and remaining actuated until said cycle marking relay has been energized, and field start means at each station responsive to a change in the condition of any device at that station to be indicated in the control office and effective only if said line circuit is energized with current of said particular polarity for momentarily opening said line circuit to actuate said electro-responsive stick relay means.

6. In a communication system of the character described; a plurality of different field stations each provided with a code transmitter operable through cycles of operation to transmit indications to a distant control office; lockout means rendering said transmitters effective only one station at a time; a cycle marking relay for each transmitter operated at the beginning and throughout each operating cycle of its transmitter and restored to a non-operated position at the end of each cycle of operation of its transmitter; a plurality of changeable devices at each field station; a change storing relay at each field station; a slow acting device for each transmitter operated to an active condition at the beginning of each cycle of operation of the system unless it is already energized and remaining in an active condition until after an interval of time following the end of an operating cycle of the system which time is slightly greater than the time said cycle marking relay is inactive between consecutive cycles of operation, whereby said slow acting device is maintained active between consecutive cycles of operation; circuit means for picking up said change storing relay upon a change in any one of said changeable devices only providing the said slow acting device is in its inactive condition; and stick circuit means

for said change storing relay maintained closed until that station has transmitted the indications of its changeable device; whereby the group of stations having new indications to transmit at a given time act to transmit indications one station at a time in turn before any other station can transmit its indications even though a change should occur in the changeable devices at that other station prior to the transmission of indications from said group of stations.

- 5 7. In a code communication system for transmitting indications of the conditions of changeable devices from a plurality of field stations during different operating cycles; a normally at rest code transmitting apparatus at each station operable to transmit, when set into operation, an indication code during a cycle of operation; lock-out means associated with said stations for allowing only one station at a time to transmit when more than one station is ready to transmit; a slow acting relay at each station picked up at the beginning of each cycle of operation of the system unless it was already up and maintained picked up throughout such cycle and also between consecutive cycles when several stations transmit successively without a prolonged intervening period of rest; and starting means at each station responsive to a change in the condition of a changeable device at that station for rendering the code transmitting apparatus at that station operable if said lock-out means permits such operation, said starting means being rendered active only between cycles of operation and then only if said slow acting relay is in its released condition and when rendered active remaining active until said lock-out means has allowed its code transmitting apparatus to operate, whereby, upon successive changes at the several stations occurring faster than normal operation of the system can handle, the stations are caused to transmit indications in groups each group including those stations where changes have occurred since the last preceding prolonged period of rest.
- 15 8. In a code communication system for transmitting indications of the existing condition of changeable devices from a plurality of field stations to a control office during different operating cycles, a line circuit connecting the control office and the several field stations, a code transmitter at each field station operable to control the energization of said line circuit to form an indication code characteristic of that station and the existing condition of the changeable devices at that station, lock-out means for controlling the operation of said code transmitted to allow the operation of the transmitters only one station at a time during an operating cycle, and apparatus at each field station comprising, a cycle marking relay assuming its inactive at rest condition at the end of each operating cycle of the system after a time interval of delay, a slow-release relay energized at the beginning of each operating cycle of the system unless it was already energized and maintained in its energized condition to the end of each cycle for a time interval longer than the period of rest between consecutive cycles of the system; a change relay operated in response to a change in the condition of any one of the changeable devices at the corresponding station, a change repeater relay energized by the operation of said change relay only if said cycle marking relay is in its inactive condition and said slow-release relay is also in its released condition, said change repeater relay
- 20 25 30 35 40 45 50 55 60 65 70 75

acting to cause operation of a corresponding code transmitter if said lockout means permits such operation, and a stick circuit for maintaining said change repeater relay energized until the corresponding code transmitter has operated, whereby the change repeater relays of the groups of stations having their change relays operated prior to the energization of said slow release relay may cause their indications to be transmitted during a series of consecutive cycles one cycle for each change repeater relay energized before the change repeater relay at any other station can be energized to cause operation of its code transmitter.

9. In a code communication system of the character described, a normally energized line circuit connecting a control office and a field station and including a source of energy in the control office, a line relay at the control office and another line relay at the field station, cycle marking means at said station and at the control office non-responsive in its inactive condition to the normal energization of said line circuit, means at said station responsive to a temporary opening of said line circuit for rendering said cycle marking means responsive to the intermittent energization of said line circuit during a cycle of operation to cause it to become active at the beginning of the cycle and remain active throughout such cycle, step-by-step means at the control office and at the field station operated in synchronism in response to repeated operation of said line relays to comprise a cycle of operation only when said cycle demarking means is in an active condition, an impulsive relay at the field station controlled by said step-by-step means at the station so as to be effective to alternately open and close said line circuit for each step to impress a series of time spaced impulses of normal lengths thereon, changeable devices at the field station having indications to be transmitted, a normally deenergized space timer relay for when energized causing said impulsive relay to make a space period of abnormal length, a pick-up circuit for said space timer relay closed or left open during each step in accordance with the indication to be transmitted during the space period for that step, means at the control office distinctively responsive to the normal or the abnormal space periods on each step of said step-by-step means at the control office to register the indications transmitted, means for momentarily opening said line circuit on a change in the condition of said devices only providing said line circuit is normally energized, and circuit means maintaining said cycle marking means active irrespective of the open condition of said line circuit during a prolonged time space period produced by said space timer relay.

10. In a code communication system of the character described for two-way communication between a control office and a field station through the medium of a repeater station, a main line circuit connecting the control office and the repeater station, a repeater line circuit connecting the repeater station and the field station, a line relay in said main line circuit at the control office and a polar line relay in said main line circuit at the repeater station, a line relay in said repeater line circuit at the repeater station and a polar line relay in said repeater line circuit at the field station, a source of energy at the control office, a source of energy at the repeater station, step-by-step means at the control office and at the field station each responsive

to the line relay at its respective location, transmitting means at the control office operable to energize said main line circuit from said control office source with a series of impulses of selected polarities, control repeat transmitting means at the repeater station controlled by said polar line relay in said main line circuit for energizing said repeater line circuit from said repeater source with a series of impulses of polarities corresponding with the polarities of the impulses being impressed on said main line circuit at the control office, means for applying steady potential of one polarity to said main line circuit from said control office source without interruption when said control office transmitting means is inactive, means for applying steady potential of said one polarity to said repeater line circuit from said repeater station source without interruption when said control office transmitting means is inactive, transmitting means at the field station at times effective to open and close said repeater line circuit for time intervals of selected lengths, indication repeat transmitting means at the repeater station controlled by said line relay in said repeater line circuit at such station for opening and closing said main line circuit to effect a series of impulses of selected lengths on said main line circuit corresponding with the series of impulses being impressed on said repeater line circuit by the operation of said field station transmitting means, and lock-out means at said repeater station for allowing only said control repeat transmitting means or said indication repeat transmitting means to function during a particular series of impulses depending upon whether or not said field station opens said repeater line circuit for a series of impulses prior to the application of the initial impulse of a series of impulses impressed on said main line circuit at the control office.

11. In a code communication system of the character described for transmitting indications from each of a plurality of field stations to a control office, a line circuit extending from the control office to the most distant field station and including in series a relay at each station, step-by-step means at each of the field stations responsive to the operation of the corresponding line relay, a source of energy applied to said line circuit at the control office, transmitting means at each field station operable to control said line circuit to create a series of impulses therein separated by time spaces, each impulse being of a selected character in accordance with indications to be transmitted, and means at each station for predetermining that the number of impulses transmitted by said transmitting means in one cycle of operation is in accordance with the number of indications to be transmitted from that station, irrespective of the number of steps provided, whereby the length of each cycle of operation for the transmission of indications is determined by the number of indications to be transmitted from the station transmitting, irrespective of variations in the number of indications provided for each of the different field stations.

12. In a code communication system of the character described for transmitting indications from each of a plurality of field stations to a control office, a line circuit extending from the control office to the most distant field station and including in series a relay at each station and at the control office, step-by-step means operable

through a predetermined number of steps at each of the field stations and at the control office, responsive to the operation of the corresponding line relay, a source of energy applied to said line circuit at the control office, a transmitting relay at each field station operable in response to said step-by-step means at that station to open and close said line circuit to effect a series of impulses therein separated by time spaces, each impulse and each time space being of a selected duration in accordance with indications to be transmitted, means for rendering each of said transmitting relays ineffective to close said line circuit after all indications have been transmitted from that station until the system has entered a period of rest, irrespective of additional steps provided at that station, and code receiving means at the control office capable of receiving each indication code, irrespective of the number of characters in that code.

13. In a code receiving system for receiving multiple impulse codes of which each impulse is distinctive by being either relatively long or relatively short, the combination with a line circuit extending from a transmitting station upon which are superimposed a series of impulses of current distinctive in character by being either relatively long or relatively short, a line relay included in said line circuit at said receiving station, a line repeater relay controlled by said line relay, step-by-step means controlled by said line repeater relay, relay means controlled by said step-by-step means, a detector relay at said receiving station having an energizing winding controlled by circuits in multiple through the medium of said line relay and said relay means so that said winding will remain energized so long as said current impulses are relatively short to an extent that said line relay assumes its deenergized position before said relay means responds to the picking up of said line relay, and an indicator controlled by said detector relay and said step-by-step means.

14. In a code receiving system for receiving multiple impulse codes of which each time space between adjacent impulses is distinctive by being either relatively long or relatively short, the combination with a line circuit extending from a transmitting station upon which are superimposed a series of impulses of current distinctive by being either relatively long or relatively short, a line relay included in said line circuit at said receiving station, a line repeater relay controlled by said line relay, step-by-step means controlled by said line repeater relay, relay means controlled by said step-by-step means, a detector relay at said receiving station having an energizing winding controlled by circuits in multiple through the medium of said line relay and said relay means so that said winding will remain energized so long as the time spaces between said current impulses are relatively short to an extent that said line relay assumes its energized position before said relay means responds to the dropping of said line relay but will be deenergized for each relatively long impulse, and an indicator controlled by said detector relay and said step-by-step means.

15. In a code receiving system for receiving multiple impulse codes of which each impulse and time space is distinctive by being either relatively long or relatively short, the combination with a line circuit extending from a transmitting station and transmitting a series of impulses of current separated by time spaces over said line

circuit, said impulses and time spaces being distinctive by being either relatively long or relatively short, a line relay included in said line circuit at said receiving station, step-by-step means at said receiving station controlled by said line relay, relay means at said receiving station controlled by said step-by-step means, a first detector relay at said receiving station having an energizing winding controlled by contacts on said line relay and contacts on said relay means so that said winding will remain energized so long as said current impulses are relatively short to an extent that said line relay assumes its deenergized position before said relay means has responded to the picking up of said line relay but will have its winding deenergized in response to a relatively long impulse as a result of response of said relay means to the picking up of said line relay before said line relay has again assumed its deenergized position, a second detector relay at said receiving station having an energizing winding controlled by contacts on said line relay and contacts on said relay means so that said winding will remain energized so long as the time spaces between such impulses are relatively short to an extent that said line relay assumes its energized position before said relay means has responded to the dropping of said line relay but will have its winding deenergized in response to a relatively long time space as a result of response of said relay means to the dropping of said line relay before said line relay has again assumed its energized position, and indicators controlled by said step-by-step means and said detector relays.

16. Receiving apparatus for a code communication system in which impulses of long or short duration spaced by time intervals of long or short duration are transmitted over a line circuit connecting two stations comprising; step-by-step means at the receiving station responsive to the opening and closing of said line circuit at the transmitting station, a first detector relay at the receiving station having its winding maintained energized through contacts controlled by said step-by-step means for one or more impulses so long as said line circuit is closed for relatively short periods of time during such impulses, and dropped away by deenergization of its winding during each relatively long period of closure of the line circuit, and a second detector relay at the receiving station having its winding maintained energized through contacts controlled by said step-by-step means for one or more impulses so long as said line circuit is opened for relatively short periods of time between such impulses, and dropped away by deenergization of its winding during each relatively long period of opening of the line circuit, the energization of the windings of said detector relays being controlled by the same relays and step-by-step means whereby a receiving station detects the length of each impulse and the length of each time space by the time of operation of said step-by-step means.

17. Receiving apparatus for a code communication system in which impulses of long or short duration spaced by time intervals of long or short duration are transmitted over a line circuit connecting two stations comprising; step-by-step means at the receiving station responsive to the opening and closing of said line circuit, a first detector relay at the receiving station having its winding maintained energized through contacts controlled by said step-by-step means for one or

more steps of said step-by-step means as long as the periods of closure of said line circuit are relatively short, and dropped away during each period of closure of said line circuit that is relatively long, and a second detector relay at the receiving station having its winding maintained energized through contacts controlled by said step-by-step means for one or more steps of said step-by-step means so long as the periods of opening of said line circuit are relatively short and dropped away during each relatively long period of opening of the line circuit, whereby the receiving station detects by its step-by-step means the length of each impulse and the length of each time space between impulses applied to said line circuit.

18. Apparatus for a system of code communication including a line circuit connecting a transmitting station and a receiving station over which may be transmitted a code which consists of a series of electrical impulses, derived from a source of current at said receiving station, which are distinctive by being either relatively long or short and separated by time spaces distinctive by being either relatively long or short; code creating means comprising, a pulsing relay having a front contact included in said line circuit, a first slow-dropping relay for when picked up making a normally short impulse long, a second slow-dropping relay for when picked up making a normally short time space long, step-by-step means controlled by said line circuit for intermittently applying a source of current to said pulsing relay through a pick-up circuit including a back contact of said second slow-dropping relay, a stick circuit for said pulsing relay including a front contact of said first slow-dropping relay, means including said step-by-step means for during a time space preceding a long impulse picking up said first slow-dropping relay, and means including said step-by-step means for during an impulse preceding a long time space picking up said second slow-dropping relay, whereby a time space may be made long because the pick-up circuit of said pulsing relay is held open by said second slow-dropping relay and an impulse may be made long by the prolonged closing of said stick circuit for said pulsing relay by said first slow-dropping relay.

19. Apparatus for a system of code communication including a line circuit connecting a transmitting station and a receiving station and having a source of current therein at said receiving station over which may be transmitted a code which consists of a series of electrical impulses distinctive by being either relatively long or short and separated by time spaces distinctive by being either relatively long or short; code creating means comprising, a line relay at the transmitting station included in series in said line circuit, step-by-step means at said transmitting station controlled by said line relay, an impulsing relay at said transmitting station controlled by said step-by-step means at that station to be effective to alternately open and close said line circuit for each step to impress a series of time spaced impulses of normal lengths thereon, a normally deenergized impulse timer relay for when energized to cause said impulsing relay to make an impulse of abnormal length, a pick-up circuit for said impulse timer relay closed or left open during each step in accordance with the indication to be transmitted during the impulse period for that step, a normally deenergized space timer relay for when energized to cause said impulsing

relay to make a space period of abnormal length, and a pick-up circuit for said space timer relay closed or left open during each step in accordance with the indication to be transmitted during the space period for that step.

20. In a remote control system, a line circuit connecting a plurality of stations, a movable device at each station, a code transmitter at each station each operating when initiated to deliver a code indicating the condition of the associated movable device to said line circuit, means responsive to a change in the condition of each movable device for initiating the operation of the associated code transmitter, lock-out means effective if a plurality of code transmitters are initiated simultaneously to discontinue the operation of all but one, storing means causing the remaining transmitters which have been initiated to transmit their codes subsequently, one at a time in an order dependent upon the relative superiority of the different stations, and means preventing the initiation of the code transmitter at each superior station in response to a change in the condition of a movable device at such station occurring while inferior stations have codes stored for transmission until all of said stored codes have been transmitted.

21. In a remote control system, a line circuit connecting a plurality of stations, a movable device at each station, a code transmitter at each station each operating when initiated to deliver a code indicating the condition of the associated movable device to said line circuit, means for initiating each code transmitter in response to a change in condition of the associated movable device, lock-out means effective if the devices at different stations have changed their condition prior to the initiation of a code at one of such stations to cause the different codes to be delivered one at a time to the line circuit in a predetermined order dependent upon the relative superiority of the different stations, and means delaying the initiation of any code in response to a subsequent change in the condition of a movable device, irrespective of the relative superiority of such station, until all of said different codes have been transmitted.

22. In a code receiving system for receiving indications from a field station, a line circuit connecting the receiving station and the field station, a source of energy applied to said line circuit at said receiving station, a line relay in said receiving station for detecting current impulses and time spaces in said line circuit, step-by-step means at the receiving station responsive to current impulses of short and long durations spaced by time spaces of short and long duration, a first relatively quick acting detector relay at the receiving station having its winding maintained energized by contacts controlled by relays controlled by said step-by-step means and contacts of said line relay for one or more impulses so long as said impulses are relatively short and dropped away by deenergization of its winding during each relatively long impulse, and a second relatively quick acting detector relay at the receiving station having its winding maintained energized through contacts controlled by relays controlled by said step-by-step means and contacts of said line relay for one or more impulses so long as said impulses are relatively short and dropped away by deenergization of its winding during each relatively long impulse, whereby a receiving station detects the length of each impulse and the length of each time space by the

time of operation of said step-by-step means and relays directly repeating the same.

23. In a code receiving system for receiving indications from a field station, a line circuit connecting the field station and a receiving office including a source of energy at said receiving office and intermittently opened at the field station to characterize a code of long and short impulses and time spaces, step-by-step means at said receiving office responsive to the opening and closing of said line circuit, a first detector relay at said receiving office having its winding maintained energized through contacts controlled by said step-by-step means for one or more steps of said step-by-step means as long as the periods of closure of said line circuit are relatively short and dropped away during each period of closure of said line circuit that is relatively long, and a second detector relay at said receiving office having its winding maintained energized through contacts controlled by said step-by-step means for one or more steps of said step-by-step means so long as the periods of opening of said line circuit are relatively short and dropped away during each relatively long period of opening of said line circuit, whereby the receiving office detects by the time of operation of its step-by-step means the length of each impulse and the length of each time space between impulses applied to said line circuit.

24. In a remote control system, a line circuit connecting a plurality of stations, a movable device at each station, a code transmitter at each station each operating when initiated to deliver a code indicating the condition of the associated movable device to said line circuit, means responsive to a change in the condition of each movable device for initiating the operation of the associated code transmitter, lock-out means effective if a plurality of the movable devices change their condition before their respective code transmitters are initiated to segregate the respective field stations at which said plurality of movable devices and their respective code transmitters are located into a group and to render but one of said code transmitters effective at a time until a code reflecting the condition of each of said movable devices of said group has been transmitted, whereby a plurality of stored codes of a particular group of field stations are transmitted one at a time in a pre-determined order, and means preventing the ini-

5 tiation of any other transmitter in response to a subsequent change in condition of a movable device at a field station not included in that group until all of said stored codes have been transmitted.

25. In a remote control system, a line circuit connecting a plurality of stations, a movable device at each station, a code transmitter at each station each operating when initiated to deliver 10 a code indicating the condition of the associated movable device to said line circuit, a code sending relay at each station, means responsive to the actuation of a code sending relay and rendered effective when the line circuit has been free for at least a brief interval at the end of a code to initiate the associated code transmitter, means restoring each actuated code sending relay to normal when the associated code transmitter has delivered its code, timing means set into operation 15 at each station at the end of each delivered code from that or any other station and completing its operation only if the line circuit remains free for a time greater than said brief interval, and means for actuating each code sending relay in response to a change in condition of the associated movable device but effective only upon the completion of the operation of said timing means.

26. In a remote control system, a line circuit connecting a plurality of stations, a movable device at each station, a code transmitter at each station each operating when initiated to deliver 20 a code indicating the condition of the associated movable device to said line circuit, means for initiating each code transmitter in response to a change in condition of the associated movable device, lock-out means effective if the devices at different stations have changed their condition prior to the initiation of a code at one of such stations to separate these different stations into 25 a group and cause the different codes of the stations of that group to be delivered one at a time in a predetermined order, and means delaying the initiation of a code at any station not included in that group in response to a change in the condition of a movable device thereat which occurs during the transmission of said different codes of the stations in said group until all of said different codes have been transmitted.
